TELEPHONE SYSTEM

Edward S. Peterson, Elmwood Park, Ill., assignor
to Associated Electric Laboratories, Inc., Chi-
cago, Ill., a corporation of Delaware

Application December 27, 1938, Serial No. 247,837

30 Claims. (Cl. 179—26)

The present invention relates to telephone systems and more particularly to improvements in telephone systems including exchanges of the remotely controlled type wherein the automatic switching apparatus of two or more tandem connected small automatic exchanges is controllable from a main or central exchange to set up connections between the lines extending to the sub-exchanges.

10 In a system of the character indicated, the automatic switching apparatus provided in the sub-exchanges is usually controllable from an operator's position in the main or central exchange over trunk lines interconnecting the exchanges. 15 The automatic switching apparatus provided in each of the sub-exchanges conventionally comprises one or more finder-connector links. Usually, a single link in each exchange is sufficient to provide reasonably good service to the 20 small number of lines extending to the associated exchange. With such an arrangement, the switching apparatus provided in the tandem connected sub-exchanges can serve only one calling line at a time and, hence, it is necessary to provide, in conjunction with the automatic switching apparatus, a lockout arrangement for guarding 25 an established connection against intrusion occasioned by other calls. It is also desirable that calls, initiated at a time when the automatic switching apparatus provided in the sub-exchanges is busy, be stored until the apparatus 30 is freed and then forwarded to the control operator in the main or central exchange.

It is, therefore, an object of the present invention to provide, in a tandem exchange system of the character described, an improved line lockout and call storing arrangement which is operative to guard an established connection against intrusion and to forward a waiting call to the central exchange operator's position when the automatic switching apparatus provided in the tandem connected sub-exchanges is released.

It is a further object of the invention to provide, in a system of the character described and including two tandem connected sub-exchanges, an improved arrangement for rendering the finder switch embodied in the automatic switching apparatus of one of the sub-exchanges inactive when a call is initiated on a line extending to the other subexchange or on the trunk line extending to the operator's position in the central exchange.

It is a still further object of the invention to provide, in a system of the character described, an improved arrangement for storing a call in-

itiated on one of the lines extending to one of the sub-exchanges at a time when the automatic switching apparatus of the tandem connected sub-exchanges is busy and for initiating the operation of the finder switch having access to the line upon which the stored call was initiated when the automatic switching apparatus becomes idle.

In the illustrated embodiment of the invention, there are provided a main or central exchange in which the operator's position equipment is located, a tandem exchange and a sub-exchange, together with a first trunk line extending between the main and tandem exchanges and a second line extending between the tandem and sub-exchanges. The sub-exchange terminates a plurality of subscribers' lines and has provided therein automatic switching apparatus controllable over the indicated first and second trunk lines from the operator's position in the main exchange to set up connections between calling and called ones of the subscribers' lines. More particularly, this automatic switching apparatus includes a finder switch having access to the subscribers' lines and normally operative to select a calling line therefrom, and a connector switch controllable from the operator's position to select a called one of the subscribers' lines. The tandem exchange similarly comprises automatic switching apparatus terminating a plurality of additional lines and controllable over the above-mentioned first trunk line from the operator's position in the main exchange to set up connections between calling and called ones of the additional lines. The automatic switching apparatus provided in the tandem exchange is also utilized in establishing connections between the subscribers' lines extending to the sub-exchange and comprises a second finder switch and a connector switch each having access to the lines extending to the sub-exchange and to the second trunk line which interconnects the tandem exchange with the sub-exchange.

In accordance with one feature of the present invention, there is provided in the sub-exchange apparatus controllable over the second trunk line, mentioned above, and operative in response to the initiation of a call on one of the additional lines extending to the tandem exchange for preventing the finder switch located in the sub-exchange from operating. Through this arrangement a connection resulting from a call initiated on one of the lines extending to the tandem exchange is guarded against intrusion occasioned by a call initiated on one of the lines extending

to the subexchange. This apparatus is also operative to prevent the finder switch located in the subexchange from operating when a call is initiated on the first trunk line extending between the main and tandem exchanges. More particularly, the apparatus for rendering the finder switch located in the subexchange inactive comprises a group of relays which are operative to open a point in the operating circuit 10 for the operating magnet of the indicated finder switch in response to the application of a predetermined potential, namely, negative battery potential, to one of the conductors of the trunk line extending between the tandem exchange and 15 the subexchange. In the tandem exchange there is further provided a lockout relay which operates to apply this predetermined potential to the indicated trunk line conductor when the finder switch provided in the tandem exchange operates to seize a calling one of the subscribers' lines extending to the tandem exchange. Following the operation of the apparatus described above, if a second call is initiated on one of the lines extending to the subexchange, means comprising 20 the line relay associated with the calling line are provided for storing the call until the automatic switching apparatus provided in the tandem exchange and the subexchange is released. Apparatus jointly controlled by the storing means just 25 mentioned and the lockout apparatus described above is also provided for initiating the operation of the finder switch in the subexchange to seize the calling line when the busy condition of an automatic switching apparatus is terminated. 30 By virtue of this arrangement, it is unnecessary for a calling subscriber repeatedly to initiate a call to a desired substation since, when a call is once initiated, the automatic switching apparatus provided in the tandem and subexchanges 35 will ultimately route the call to the control operator's position so that the control operator can resignal the calling subscriber by ringing back over the calling line.

Further features of the invention pertain to 40 the particular arrangement of the circuit elements whereby the above and additional operating features are attained.

The novel features believed to be characteristic of the invention are set forth with particularity 45 in the appended claims. The invention, both as to its organization and method of operation, together with further objects and advantages thereof, will best be understood by reference to the specification taken in conjunction with the 50 accompanying drawings, in which Figure 1 schematically illustrates an automatic telephone system having the features of the present invention embodied therein, Fig. 2 illustrates the mode of assembling the remaining figures of the drawings 55 to form a unified system, and Figs. 3 to 8, inclusive, considered together, illustrate the details of the switching apparatus embodied in the system shown in Fig. 1.

Referring now more particularly to Fig. 1 of 60 the drawings, the system there illustrated comprises a main exchange 9, a tandem exchange 10, and two satellite or subexchanges 11 and 12 interconnected by trunk lines 13, 14 and 17. More particularly, the first trunk line 13 extends between an operator's position 15 provided in the main exchange 9 and the automatic switching apparatus provided in the tandem exchange 10, the second trunk line 14 extends between the 65 automatic switching apparatus provided in the 70 tandem exchange 10 and the automatic switch-

ing apparatus provided in the subexchange 11, and the third trunk line 17 extends between the automatic switching apparatus provided in the tandem exchange 10 and the automatic switching apparatus provided in the subexchange 12. 5

The automatic switching apparatus provided in the tandem exchange 10 comprises a finder-connector link 16 including a finder switch and a connector switch each having access to the trunk lines 14 and 17 and also to a plurality of 10 additional lines including two subscribers' lines 18 and 19 respectively extending to the substations T₁ and T₂. More particularly, the lines 14, 17, 18 and 19 individually terminate in line circuits which are diagrammatically illustrated as 15 a group at 20. The apparatus provided in the subexchange 11 similarly comprises a finder-connector link 21 including a finder switch and a connector switch each having access to a plurality of subscribers' lines including the two lines 20 indicated at 22 and 23 respectively extending to the substations T₃ and T₄. These lines have individually associated therewith line circuits which are diagrammatically illustrated as a group at 24. The switching apparatus provided 25 in the subexchange 12 is identical with that provided in the subexchange 11 and comprises a finder-connector link 25 including a finder switch and a connector switch each having access to a plurality of subscribers' lines, two of which are 30 indicated at 26 and 27 as extending to the substations T₅ and T₆, respectively. These lines individually terminate in the exchange 12 in line circuits which are diagrammatically illustrated as a group at 28. The subscribers' lines extending to the exchanges 10, 11 and 12 are of the well-known magneto type, each subscriber's substation being equipped with a hand generator or magneto for projecting ringing current over the associated line and with local batteries for voice 40 frequency current transmission. These lines may be of the single party or multiparty type as desired.

Neglecting for the present the details of the 45 automatic switching apparatus provided in the exchanges 10, 11 and 12 and considering the operation of the system generally, when a call is initiated on a line extending to any one of the three exchanges 10, 11 and 12, the call is forwarded to the operator's position 15 in the 50 main exchange 9 and the automatic switching apparatus provided in each of the three exchanges is rendered nonresponsive to calls initiated before the apparatus is thereafter released. For example, if a call intended for the substation 55 T₂ is initiated at the substation T₁, the finder switch of the finder-connector link 16 functions under the control of the line circuit individual to the calling line 18 to seize the calling line and to transmit a signal to the operator's position 60 15 indicating that a call is present on the trunk line 13 which should be answered. The control apparatus embodied in the finder-connector link 16 also functions, when the calling line 18 is seized, to apply a predetermined potential, namely, negative battery potential, to one conductor of each of the two trunk lines 14 and 17. Certain of the relays embodied in the control apparatus of the finder-connector link 21 respond to the application of negative battery potential to 65 the indicated conductor of the trunk line 14 by operating to open a point in the operating circuit for the operating magnet of the finder switch included in the link 21, thereby to render this 70 switch nonresponsive to calls initiated on lines 75 15.

extending to the subexchange 11. In a similar manner, the finder-connector link 25 provided in the subexchange 12 is locked out of service for the duration of the call initiated at the substation T_1 on the line 18.

After answering the call and ascertaining from the calling subscriber the number of the desired substation or the name of the desired party, the operator attending the position 15 dials the directory number of the desired substation in the usual manner. The calling party is expected to hang up before the dialing and ringing operations are performed by the operator. The connector portion of the link 16 responds to the dialing operation by selecting the desired called line or, in the case assumed, the line 19. Following the dialing operation, the operator actuates the ringing key provided in her cord circuit to cause ringing current to be projected over the calling and called lines, thereby to energize the signaling devices or ringers respectively provided at the calling and called substations. Finally, the desired connection is completed when the call is answered at the calling and called substations. The release of the established connection is entirely under the control of the operator attending the operator's position 15. More particularly, when the connection is no longer desired, it is expected that either the calling or the called party will operate his hand generator to transmit a disconnect signal to the control operator. Upon receiving this signal, the operator clears out the connection, permitting the operated finder-connector link 16 and the line circuits associated with the calling and called lines 18 and 19, respectively, to be released. During the release of this apparatus, battery potential is removed from the above-mentioned conductors of the trunk lines 14 and 17, respectively, with the result that the relays embodied in the links 21 and 25 operate to reprepare the circuits for energizing the operating magnets of the finder switches respectively included in these links. In this manner, the automatic switching apparatus provided in the three exchanges 10, 11 and 12 is conditioned for further use.

If the call originating at the substation T_1 associated with the line 18 and routed to the operator's position 15 is to be extended to a line terminating at one of the subexchanges 11 and 12, the operator, upon ascertaining the telephone number of the desired station, dials two digits, the first digit being utilized to cause the connector portion of the link 16 to seize the trunk line extending to the proper subexchange, as, for example, the exchange 11, and the second digit being repeated through the operated finder-connector link 16 to the connector control apparatus of the finder-connector link provided in the selected exchange. For example, if the call is to be routed to the substation T_3 associated with the line 22, the operator first dials the digit corresponding to the trunk line 14, whereby the connector portion of the link 16 is caused to seize this trunk line. The impulses of the second digit dialed at the operator's position are repeated through the control apparatus of the link 16 to the connector portion of the link 21, causing the connector switch in this link to select the desired called line 22. After the called line is selected, the operator actuates her ringing key to cause ringing current to be projected over the established connection, whereby the signaling devices respectively provided at the calling and called substations are

energized. Finally, the desired conversational circuit is fully established when the call is answered at the calling and called substations. Here again, the release of the connection is entirely under the control of the operator attending the position 15, the manner in which the release of the apparatus is effected being substantially similar to the release of the apparatus as described above.

A call originating on a line extending to one of the subexchanges is first routed through the automatic switching apparatus of the corresponding exchange and is then extended through the finder-connector link 16 and over the trunk line 13 to the operator's position 15. For example, if a subscriber at the substation T_3 initiates a call at a time when the automatic switching apparatus provided in the three exchanges 10, 11 and 12 is idle, the finder portion of the link 21 is caused to operate to seize the calling line 22, after which a seizing pulse of current is transmitted over the trunk line 14 to seize the link 16. The finder portion of the last-mentioned link, in turn, operates to seize the calling trunk line 14 and to transmit a splash of signaling current to the operator's position 15. When the finder switch of the link 16 operates to seize the line 14, the control apparatus of the link 16 functions to impress negative battery potential upon one conductor of the trunk line 17, and the control apparatus of the link 25 provided in the exchange 12 responds by rendering the finder portion of the link 25 nonresponsive to calls initiated on the lines extending to the exchange 12. The call signal device provided at the operator's position 15 responds to the splash of signal current by operating to signal the operator that an incoming call on the trunk line 14 should be answered. After answering the call and conversing with the calling subscriber to ascertain the directory number of the desired substation, the operator may cause the desired connection to be set up by dialing the appropriate line selecting digits in the manner explained above. For example, if the call is to be forwarded to a substation on the line 18, the operator dials the single digit designating this line to cause the connector portion of the link 16 to seize the called line. Alternatively, the call may be forwarded to another line terminating at the exchange 11, in which case the operator dials the two digits of the directory number designating the called line. The connector portion of the link 16 responds to the impulses of the first digit by seizing the trunk line 14 and establishing a pulsing circuit including the conductors of this trunk line over which the impulses of the second digit may be transmitted to the connector portion of the link 21. The impulses of the second digit are then repeated through the control apparatus of the link 16 and over the established pulsing circuit including the trunk line 14 to the connector switch of the link 21, and this switch responds by seizing the desired called line. If the call forwarded to the operator's position 15 from the calling line 22 is to be routed to a subscriber's line terminating at the subexchange 12, the operator first dials the digit designating the trunk line 17, whereby the connector portion of the link 16 is caused to operate to seize the line 17 and the connector portion of the link 25 is conditioned to respond to the impulses of the second digit designating the desired called line. In any case, after the dialing operation is completed, the operator actuates her ringing key to cause ringing current to be projected over the calling and

called lines and the desired connection is fully completed when the call is answered at the calling and called substations.

Calls routed to the operator's position 15 from lines extending to the main exchange 9 may be routed, under the control of the operator attending the position, over the trunk line 13 to any one of the subscriber's lines terminating in the exchanges 10, 11 and 12. To this end, the operator seizes the trunk line 13 and dials the directory number of the desired line, the connector switches of the links provided in one or more of the exchanges 10, 11 and 12 responding to the dialed impulses by establishing a connection including the trunk line 13 to the desired line in the manner previously explained. When the line 13 is initially seized, the finder switch of the link 16 is rendered nonresponsive to calls initiated on the subscribers' lines extending to the exchange 10, and the control apparatus of the link 16 operates to impress negative battery potential upon one conductor of each of the trunk lines 14 and 17. The control apparatus respectively included in the links 21 and 25 responds to this potential by operating to render the finder switches of the two enumerated links nonresponsive to calls initiated on the lines to which they have access.

As explained above, in all instances where a call is initiated on the trunk line 13 or on a line terminating at one of the three exchanges 10, 11 and 12, the automatic switching equipment respectively provided in the three exchanges is rendered nonresponsive to other calls initiated on other lines before the automatic switching apparatus is released. To eliminate the necessity for a subscriber repeatedly to initiate a call in order to obtain access to the automatic switching apparatus after it becomes idle, provisions are made whereby a call, originated at a time when the automatic switching apparatus is busy, is stored until the automatic switching apparatus is released and is then automatically forwarded to the operator's position 15 in the exchange 9. For example, if a call is initiated on the line 22 at a time when the automatic switching apparatus provided in the three exchanges 10, 11 and 12 is busy, the combined line, cut-off and call storing relay associated with the line 22 operates and remains operated even though the calling subscriber abandons the call. Thereafter and when the automatic switching apparatus is released, the operated line relay associated with the line 22, in conjunction with certain of the apparatus embodied in the link 21, functions to initiate the operation of the finder portion of the link 21 to seize the line 22. From this point on, the manner in which the call is forwarded to the operator's position 15 in the main exchange 9 is exactly the same as described above. In a similar manner, calls originating on lines extending to the exchanges 10 and 12 at times when the automatic switching apparatus is busy are stored until the switching apparatus is released, after which they are automatically forwarded to the operator's position 15. The operator attending this position, upon answering such a call and failing to receive a response from the calling subscriber, may ring back over the calling line to signal the calling substation, and hence it is unnecessary for the calling subscriber to attend the calling substation during the interval when the automatic switching apparatus is busy.

Referring now in greater detail to the switch apparatus embodied in the system and considering the equipment provided at the operator's po-

sition 15, this equipment comprises, as shown in the right-hand portion of Fig. 3, a repeating transformer 370 having primary windings 373 and 374 terminating the conductors of the trunk line 13, and secondary windings 371 and 372 connected by means of conductors C385 and C386 to the contacts of a call and answer jack 369 through which the trunk line 13 is rendered accessible to the operator's cord circuit. This equipment further includes a signal device in the form of a drop 375 which is energized over the trunk line 13 on calls incoming to the operator's position 15 when the exchange battery provided in the tandem exchange 11 is connected across the line conductors C367 and C368. There is also provided at the operator's position 15 a calling key 380 and a calling or impulsing device 382 which is operative in the usual manner to deliver current pulses through the springs of the calling key 380 and over the trunk line 13 to the control apparatus of the finder-connector link 16 provided in the tandem exchange 10.

As previously indicated, the subscriber's line extending to the tandem exchange 10 are of the well-known magneto type and each thereof may have associated therewith a plurality of substations of the character diagrammatically illustrated at T₁ and T₂. At each substation there is provided a manually operable magneto or hand generator which is utilized in the initiation of calls, the generators of this character provided at the substations T₁ and T₂ being indicated at 683 and 691, respectively. The line circuit associated with the line 18 comprises a relay R680 which is arranged to perform all of the functions incident to the initiation and completion of calls involving the line 18. More particularly, this relay functions as a combined line, cut-off and call storing relay. An identical line circuit, schematically indicated at 690, is provided in association with the subscriber's line 19.

The line circuits individually associated with the trunk lines 14 and 17 extending to the tandem exchange 10 are of different arrangement than the line circuits individually associated with the subscriber's lines. More particularly, the line circuit associated with the trunk line 14 comprises a line relay R630, a line switching relay R610, and a slow-to-operate cut-off relay R620. The line circuit associated with the trunk line 17 similarly comprises line, cut-off and line switching relays R670, R660 and R650, respectively. The two line circuits just described are arranged partially to be controlled by a common lockout relay R640, which relay functions to apply negative battery potential to one line conductor of each of the two trunk lines 14 and 17 when a call is initiated on the trunk line 13 or one of the other lines extending to the exchange 10.

The finder-connector link 16 embodied in the tandem exchange 10 comprises a finder switch 500 and a connector switch 550, both of which are of the well-known rotary step-by-step type. More particularly, the rotary finder switch 500 comprises four sets of contacts 505 to 508, inclusive, each including eleven contact points, wipers 501 to 504, inclusive, individually associated with the enumerated contact sets, and means comprising an operating magnet 530 and a ratchet and pawl mechanism, not shown, for driving the enumerated wipers over the contacts of their respective associated contact sets. For the purpose of controlling the operation of the finder switch to seize a calling one of the lines 75.

extending to the exchange 10, there are provided in the control apparatus of the link a pulsing relay R510 and a finder start relay R520. The rotary connector switch 550 comprises four sets of contacts 555 to 558, inclusive, four wipers 551 to 554, inclusive, individually associated with the enumerated contact sets, an operating magnet 540 for driving the wipers over the contacts of their associated contact sets, and a set 10 of off-normal springs 542 which are operated into engagement when the enumerated wipers are moved to their respective first off-normal positions.

The control apparatus of the link 16 includes, 15 in addition to the finder start and pulsing relays R520 and R510, respectively, a line relay R330, a slow-to-release hold relay R320, a slow-to-release pulse responsive control relay R455, a pair of control relays R440 and R470, and a pair of 20 digit responsive transfer relays R460 and R465. This apparatus further comprises a line test relay R410, an alternating current control relay R450, a pendulum type timing relay R480, a slow-to-operate link release relay R310 under the 25 control of the pendulum relay R380, and two line switching and control relays R420 and R430. For the purpose of transmitting a splash of battery current over the trunk line 13 to the operator's position 15 when the link 16 is seized, there 30 are also provided in the control apparatus of this link two additional relays R350 and R355, the first of which is of the slow-to-operate type and the second of which is slow-acting. In order to transmit a waiting tone to a calling subscriber 35 after the link 16 is seized, there is provided a tone relay R340 which functions to impress an alternating signal voltage across the secondary line terminals of the repeater 360. For the purpose of releasing the finder-connector link 16 in the 40 event a call routed by way thereof to the operator's position 15 is not answered within a predetermined time interval after the link is seized, there is also provided a link release relay 387 of the thermal type.

45 As previously indicated, the lines terminating at the subexchange 11 are also of the magneto type, each substation being provided with a hand generator adapted for use in initiating calls. The hand generators provided at the substations 50 T₄ and T₅ are indicated at 775 and 814, respectively. The line circuits associated with these lines are of identical arrangement with the line circuits individually associated with the subscribers' lines terminating at the tandem exchange 10. More particularly, the line circuit 55 associated with the line 22 comprises a combined line, cut-off and call storing relay R700, while the line circuit associated with the line 23 comprises a similar relay R810. The automatic switching apparatus provided in the subexchange 60 11 is, in general, similar to the apparatus embodied in the tandem exchange 10. Thus, the finder-connector link 21 comprises a finder switch 800 and a connector switch 850, both of 65 which are of the single motion rotary step-by-step type. The switch 800 comprises four sets of bank contacts 805 to 808, inclusive, each including eleven contacts, wipers 801 to 804, inclusive, respectively associated with the enumerated contact sets and means comprising an operating magnet 816 and a ratchet and pawl mechanism, not shown, for driving the enumerated wipers over the contacts of their respective associated contact sets. The connector switch 850 is of 70 similar construction but comprises only three 75

contact sets 855, 856 and 857, three wipers 851 to 853, inclusive, individually associated with the contact sets, and a driving mechanism including an operating magnet 818 for driving the enumerated wipers over the contacts of their respective 5 associated contact sets. This connector switch also includes a set of off-normal springs 827 which are operated into engagement when the wipers of the switch are stepped to their respective first off-normal positions. The control apparatus of 10 the link or, more particularly, the relay equipment embodied therein, comprises a finder start relay R825, a finder switch pulsing relay R820, and a line test relay R720 which is operative to arrest the operation of the finder switch 800 when 15 the wipers of this switch are moved to engage the contacts terminating a calling line. The control apparatus further includes a line relay R740, a slow-acting hold relay R735, a slow-to-release control relay R710, an alternating current relay R730, and a slow-to-release pulse responsive relay R830 arranged for parallel energization with the connector switch operating magnet 818. In order to transmit a splash of battery current over the trunk line 14 to the tandem exchange 10, 25 thereby to cause seizure of the link 16 when the finder switch 800 operates to a seize a calling one of the lines extending to the exchange 11, there are provided two additional relays R755 and R760 30 which are of the slow-to-operate and slow-to-release types, respectively. For the purpose of transmitting a waiting tone to a calling subscriber following seizure of the link 21, the control apparatus of this link further includes a 35 tone relay R745 which corresponds to the similar relay R340 embodied in the link 16.

Call initiated on a subscriber's line extending to the tandem exchange

Referring now in greater detail to the operation of the system and considering first a call initiated on one of the subscribers' lines extending to the tandem exchange 10, if the call is initiated at the substation T₁ associated with the line 18, for example, the combined line, cut-off and call storing relay R680 is caused to operate. More particularly, when the calling subscriber operates the hand generator 693, alternating current is projected over the line 18 to energize the upper winding of the relay R680. The path of 50 this current may be traced as extending from one terminal of the generator 693 by way of the springs 694 which are operated into engagement when the magneto armature is turned, the line conductor C567, the upper winding of R680, 55 RA683 and C563 to the opposite terminal of the generator 693. When its upper winding is energized over this circuit, the relay R680 first operates to close the "X" contacts associated with RA684, thereby to complete a circuit including 60 the resistor 685 for energizing its lower winding. Thereafter, the relay R680 completes its operation to open, at RA683, a point in its original operating circuit as traced above and to complete, at RA682, a path including the conductor C753 65 for marking the calling line 18 in the bank contacts of the finder switch 500. At RA681, the relay R680 completes a circuit for energizing the finder start relay R520, this circuit extending from ground at RA451 by way of RA451, C485, 70 C483, RA442, RA443, C484, RA681, C484' and the winding of R520 to battery. The relay R520 now operates to prepare, at RA522, a point in the circuit, traced hereinafter, for energizing the line 75

test relay R410 when the wipers of the finder switch 500 are operated into engagement with the set of contacts terminating the conductors of the calling line 18. At RA521, the relay R520 5 completes a circuit for energizing the operating magnet 530 of the finder switch 500, which circuit may be traced as extending from ground at RA411, by way of C486, RA521, RA511 and the winding of the magnet 530 to battery. When 10 energized over this circuit, the magnet 530 actuates its associated ratchet and pawl mechanism, thereby to condition this mechanism to step the wiper of the switch 500 one step when the operating magnet is subsequently deenergized. At 15 the armature 531, the magnet 530 completes an obvious circuit for energizing the upper winding of the pulsing relay R510, which latter relay, in turn, operates to open, at RA511, a point in the above-traced circuit for energizing the magnet 20 530. When the magnet 530 is thus deenergized the associated ratchet and pawl mechanism steps the wipers of the switch 500 one step and the armature 531 is restored to open the circuit for energizing the relay R510. The relay R510 now 25 restores to recomplete the operating circuit for the magnet 530, causing this magnet to again attract the armature 531, thereby to recomplete the operating circuit for the relay R510. The interrelated operation of the pulsing relay R510 30 and the magnet 530 continues until the wipers of the switch 500 are driven into engagement with the contacts terminating the conductors of the calling line 18. More particularly, when the wiper 503 is operated into engagement with the 35 contact terminating the test conductor C573, the above-mentioned circuit is completed for energizing the upper winding of the line test relay R410 in series with the lower winding of the pulsing relay R510. This circuit extends from ground 40 at RA682 by way of C573, the wiper 503, the lower winding of R510, RA522, C492 and the upper winding of R410 to battery. When its lower winding is energized over this circuit, the pulsing relay R510 is held in its operated position 45 independently of the magnet 530 so that the stepping operation of the finder switch 500 is arrested. Also, when this circuit is completed, the relay R410 operates and completes, at RA415, a holding circuit for itself, which holding circuit 50 may be traced as extending from ground at RA441 by way of RA415 and the lower winding of R410 to battery. At RA411 and its associated resting contact, the relay R410 opens a point in the above-traced circuit for energizing the finder 55 switch operating magnet 530. At RA413 and its associated resting contact, the relay R410 opens a point in the previously traced operating circuit for the finder start relay R520, which latter relay now restores to open, at RA522, a point in 60 the previously traced circuit for energizing the lower winding of the pulsing relay R510 and the upper winding of R410 in series. The relay R510 now restores, at RA414, the relay R410 completes a path for short-circuiting the lower winding of 65 the line relay R680, this path extending from ground at RA452 by way of RA414, C491, the wiper 504, the conductor C577, the lower winding of R680 and RA684 to ground. When its lower winding is short-circuited over this path, the 70 relay R680 restores to reconnect its upper winding across the conductors of the line 18.

At RA411 and its associated working contact, the relay R410 completes a circuit for energizing the lockout relay R640, this circuit extending 75 from ground at RA411 by way of C482 and the

winding of R640 to battery. Upon operating, the relay R640 completes paths for impressing negative battery potential upon one of the line conductors of each of the two trunk lines 14 and 17. Thus, at RA643 and its associated working contact, the relay R640 completes a path extending by way of the resistor 646, RA621, RC614 and RA613 for impressing negative battery potential upon the conductor C767 of the trunk line 14. Similarly, at RA642, the relay R640 completes a path extending by way of the resistor 645, RA661, RC654 and RA653 for impressing negative battery potential upon the conductor C604 of the trunk line 17. At RA644, the relay R640 opens a point in the holding circuit, traced hereinafter, 10 for the line relay R530 and prepares a point in the holding circuit, traced hereinafter, for the cut-off relay R620. At RA641, the relay R640 similarly opens a point in the locking circuit for the line relay R679 and prepares a point in the 15 holding circuit for the cut-off relay R660.

When negative battery potential is impressed upon the conductor C767 of the trunk line 14, the control apparatus of the link 21, shown in Figs. 7 and 8, operates to open a point in the operating 20 circuit for the finder switch operating magnet 816. More particularly, when the negative terminal of the battery provided in the tandem exchange 10 is connected to the trunk line conductor C767, the line relay R740 is energized 25 over a circuit including this line conductor, RA764 and the winding 752. When energized over this circuit, the line relay R740 operates to complete, at RA741, an obvious circuit for energizing the slow-acting hold relay R735. The 30 hold relay, in turn, operates to complete, at RA736, a circuit for energizing the slow-to-operate relay R755 and, at RA737, a circuit for energizing the slow-to-release relay R710. The relay R710, upon operating, opens, at RA711 35 and RA712, respectively, points in the operating 40 circuits, traced hereinafter, for the relays R745 and R760, respectively. The relay R755, upon operating, opens, at RA751 and its associated 45 resting contact, a point in the holding circuit for the relay R760 and prepares, at RA756 and RA757, a point in its own holding circuit. At RA758, the relay R755 opens a point in the 50 circuit, traced hereinafter, for energizing the respective lower windings of the line test relay R720 and the finder pulsing relay R820 in series. At RA759, the relay R750 opens a point in the circuit, traced hereinafter, for energizing the operating magnet 816 of the finder switch 800, 55 thereby to prevent this magnet from being energized in response to the operation of one of the line relays R700, R810, etc. Thus, the finder switch 800 is rendered nonresponsive to the initiation of calls on the lines extending to the exchange 11 throughout the period when the automatic switching apparatus provided in the tandem exchange 10 is busy. In a similar manner, the link circuit apparatus of the finder-connector link 25 provided in the subexchange 12 responds to the application of negative battery 60 potential to the conductor C604 of the trunk line 17 by operating to render the finder portion of the link nonresponsive to calls initiated on lines extending to the subexchange 12.

Continuing now with the operation of the finder-connector link 16, when the line test relay R410 operates in the manner explained above, it connects, at its armatures RA416 and RA417, the link line conductors C495 and C496 to the link line conductors C398 and C399, respectively, 75

thereby to connect the conductors C563 and C567 of the calling line 18 through to the line terminals of the repeater 360. At RA413 and its associated working contact, the relay R410 completes a circuit for energizing the upper winding of the tone relay R340, this circuit extending from ground at RA457 by way of RA451, C485, the wiper 554 and its associated home contact, C483, RA442, RA413, C392, the upper winding of R340 and the resistor 342 to battery. An obvious branch of this circuit extends through the heating element 388 of the thermal relay 387 to battery. When its upper winding is energized over the circuit just traced, the relay R340 completes, at RA341, an obvious path for short-circuiting its upper winding and, as a consequence, immediately restores and then reoperates. Thus, the relay R340 operates in the manner of a buzzer, its upper winding being alternately energized and deenergized in response to the short-circuiting action of its armature RA341. As a consequence, an induced undulating voltage is developed in the lower winding of R340 which is impressed across the link line conductors C398 and C399 over a path including the condenser 334 and the restored armature RA322 of the hold relay R320. This voltage serves to energize the receiver of the telephone instrument provided at the calling substation, thereby to indicate to the calling subscriber that the automatic switching apparatus provided in the exchange 10 is idle and that the call is being forwarded to the operator's position in the exchange 9.

The line test relay R410, upon operating, also completes, at RA412, a circuit for energizing the slow-acting relay R355, this circuit extending from ground at RA441 by way of RA412, C390, RA352, RC353 and the winding of R355 to battery. The relay R355 now operates to complete, at RA356, an obvious circuit for energizing the slow-to-operate relay R350. At its armatures RA358 and RA359 and their associated working contacts, the relay R355 connects the line conductors C367 and C368 of the trunk line 13 to opposite terminals of the exchange battery provided in the exchange 10, thereby to complete a circuit for energizing the drop 375 provided at the operator's position 15 in the exchange 9. More particularly, this drop or signal device is energized over a circuit extending from ground by way of RA359, C368, the winding 374, the switch springs 377 and 376, the winding of the drop 375, the winding 373, C367, RA358 and the resistor 357 to battery. The drop 375 now operates to signal the operator attending the position 15 that an incoming call on the trunk line 13 should be answered. Shortly following the operation of the relay R355, the slow-to-operate relay R350 operates to complete, at RA351 and RA352, a holding circuit for itself, which holding circuit extends from ground at RA441 by way of RA412, C390, RA352, RA351 and the winding of R350 to battery. At RA352 and RC353, the relay R350 opens a point in the previously traced operating circuit for R355, causing the last-mentioned relay to restore after an interval to disconnect the line conductors of the trunk line 13 from the terminals of the exchange battery and to reconnect these line conductors to the line terminals of the repeating transformer windings 361 and 362. In this manner, the desired talking connection between the calling substation T₁ and the equipment provided at the operator's position 15 is fully completed.

75 As indicated previously, if the operator attend-

ing the position 15 fails to answer a call within a predetermined time interval after the finder-connector link 16 is seized, the thermal relay 387 functions to cause the release of the operated switching apparatus. More particularly, when the heating element 388 of the relay 387 is energized in response to the operation of the line test relay R410, the heat energy developed by this element causes the bimetallic strip 389 to be deflected to the right. After a predetermined time interval, the free end of this strip is moved sufficiently to bring the contacts 389' into engagement, thereby to complete an obvious circuit for energizing the line relay R330. This relay, upon operating, completes, at RA331, an obvious circuit for energizing the slow-acting hold relay R320. The hold relay, upon operating, opens, at RA322, a point in the above-traced path for impressing waiting tone voltage across the link line conductors C398 and C399, thereby to terminate the signal being received by the calling subscriber. At RA321, the relay R320 completes an obvious circuit for energizing the control relay R470, which latter relay, in turn, operates to complete, at RA475, an obvious circuit for energizing the line switching and control relay R440. At RA474, the relay R470, upon operating, prepares a point in the circuit, traced hereinafter, for energizing the slow-to-release relay R455 in parallel with the connector switch operating magnet 540. At RA472, the relay R470 also completes a multiple holding circuit for the line test relay R410, this circuit extending by way of the grounded conductor C391, RA351, RA352, C390, RA412, RA415, and the lower winding of R410 to battery. At RA471, the relay R470 prepares a holding circuit for the lock-out relay R640, which holding circuit is completed in response to the subsequent operation of the relay R440 and extends from ground at RA441 by way of RA471, C482 and the winding of R640 to battery. At RA441 and its associated resting contact, the relay R440, upon operating, opens a point in the initially completed holding circuit for the relay R410 and a point in the original holding circuit for the relay R350. At RA442, the relay R440 opens a point in the above-traced circuit for energizing the upper winding of the tone relay R340 in parallel with the heating element 388 of the thermal relay 387, thereby to arrest the operation of the tone relay and to deenergize the heating element 388. At RA444, the relay R440 completes a holding circuit for itself, this holding circuit extending from ground at RA331 by way of C396, RA444 and the winding of R440 to battery.

When the circuit for energizing the heating element 388 of the thermal relay 387 is interrupted, the bimetallic strip 389 starts to cool and is deflected to the left. After a time interval, the contacts 389' are disengaged to open a point in the operating circuit for the line relay R330. This relay now restores to open, at RA331 and its associated working contact, the operating circuit for the hold relay R320 and to complete, at RA331 and its associated resting contact, the above-mentioned circuit for energizing the relay R455 in parallel with the connector switch operating magnet 540, this circuit extending from ground at RA331 over C393 to RA474 where it divides, one branch extending through the wind-

ing of R455 to battery and the other branch extending by way of RA434 and C489 and the winding of the magnet 540 to battery. When energized over this circuit, the relay R455 operates to prepare, at RA456, an operating circuit, traced hereinafter, for the relay R460, and to open, at RA458, a point in the operating circuit for the relay R430. Shortly following the completion of the above-traced circuit for energizing the magnet 540, the hold relay R320 restores to open, at RA321, the operating circuit for the control relay R410, which latter relay, in turn, restores to open, at RA475, the operating circuit for the control relay R440. At RA472, the relay R470 opens the above-traced alternative holding circuits for the two relays R350 and R410, causing both of these relays to restore. At RA471 and its associated working contact, the relay R470, upon restoring, opens a point in the above-traced holding circuit for the lock-out relay R640, causing this relay to restore. At RA471 and its associated resting contact, the relay R470 completes a circuit for energizing the pendulum relay R480, this circuit extending from ground at RA441 by way of RA471 and the winding of R480 to battery. When the relay R480 is energized over this circuit, vibratory movement of the weighted armature RA481 is initiated, thereby intermittently to complete a circuit including the conductor C395 for energizing the relay R310. Due to its slow-to-operate characteristic, the relay R310 does not operate when intermittently energized over this circuit. At RA474, the relay R470, upon restoring, interrupts the circuit, traced above, for energizing the magnet 540 in parallel with the relay R455, causing the last-mentioned relay to restore. When the magnet 540 is deenergized, it operates to step the wipers of the connector switch 550 one step from the home position and to close the off-normal springs 542, thereby to complete a circuit for energizing the relay R430, which circuit may be traced as extending from ground by way of the springs 542, C490, RA458 and the winding of R430 to battery. Upon operating, the relay R430 completes, at RA435, an obvious holding circuit for itself and prepares, at RA433, an alternative circuit for repeatedly energizing the magnet 540 to return the wipers of the connector switch 550 to normal. After an interval, the vibration of the weighted armature RA481 ceases and this armature settles into resting engagement with its associated working contact to hold the operating circuit for the relay R310 completed. The relay R310 now operates to interrupt, at RA311, the above-traced holding circuit for the relay R440. Upon restoring, the relay R440 opens, at RA444, a further point in its holding circuit and completes, at RA443 the above-mentioned alternative circuit for energizing the magnet 540. This circuit extends from ground by way of the springs 542, C490, RA443, RA433, C488, the armature 541 and the winding of the magnet 540 to battery. Due to the circuit interrupting action of the springs associated with the armature 541, the magnet 540 operates, buzzer fashion, to drive the wipers of the switch 550 to their respective home or eleventh positions, at which time the off-normal springs 542 are opened. When these springs are opened, the holding circuit for the relay R430 is interrupted and a point is opened in the circuit, just traced, for energizing the magnet 540. Following the restoration of the relay R430, the control

apparatus of the link 16 is fully restored to normal.

When the lockout relay R640 restores in the manner explained above, it functions to disconnect negative battery potential from the conductors C767 and C604 of the trunk lines 14 and 17, respectively. When negative battery potential is removed from the conductor C767, the line relay R740, embodied in the link 21, is deenergized and restores to open, at RA741, the operating circuit for the hold relay R735, thereby to cause the sequential restoration of the hold relay, the relay R755, and the control relay R710. Before the hold relay R735 falls back, a circuit is momentarily completed for energizing the relay R830 in parallel with the connector switch operating magnet 818, this circuit extending from ground by way of RA741, RA738, C849 and through the respective windings of the magnet 818 and the relay R830 to battery. When energized over this circuit, the relay R830 operates, but without effect at this time. Shortly thereafter and when the hold relay R735 restores, the circuit, just traced, is interrupted at RA738, causing the relay R830 to restore and the magnet 818, in conjunction with its ratchet and pawl mechanism to step the wipers of the switch 850 to their respective first off-normal positions. When this occurs, the off-normal springs 827 are moved into engagement to complete an alternative circuit for energizing the magnet 818 in parallel with the relay R830, this circuit extending from ground at RA736 by way of C847, the springs 827, the armature 819 and through the respective windings of the magnet 818 and the relay R830 to battery. The resulting reoperation of the relay R830 is without effect at this time. Due to the circuit interrupting action of the springs associated with the armature 819, the magnet 818 operates, buzzer fashion, to drive the wipers of the switch 850 over the contacts of their respective associated contact sets and back to their respective home positions, at which time the off-normal springs 827 are opened. When these springs are disengaged, a point is opened in the alternative operating or release circuit for the magnet 818. Following the release operation on the part of the connector switch 850, the control apparatus of the finder-connector link 21 is fully restored to normal and this link is conditioned for further use.

If the call as routed to the operator's position 15 is answered before the thermal relay 387 operates, in the manner just explained, to initiate the release of the switching apparatus, operation of the relay 387 is arrested and the switching apparatus is maintained operated. To answer the call, the operator attending the position 15 inserts the plug terminating her cord circuit in the jack 369 and operates the calling key 380 to its off-normal position. When this key is operated to its off-normal position, the springs 376 and 377 are disengaged to open a further point in the above-traced circuit for energizing the drop 375, the drop 375 is restored to normal, and a simplex circuit is completed for energizing the line relay R330. One branch of this simplex circuit may be traced as extending from ground through the winding of R330 and by way of the winding 362, RA359, C368, the winding 374, the switch springs 371 and 378, and the pulsing springs 383 to battery. The other branch of the indicated simplex circuit extends by way of the winding of R330, the winding 361, RA358, C367, the winding 373, the switch springs 379 and 381, 75

and the pulsing springs 383 to battery. When energized over this circuit, the line relay R330 operates to cause the sequential operation of the hold relay R320 and the two control relays R470 and R440, in the order named and in the manner explained above. When the two relays R470 and R440 operate, the previously traced holding circuit for the lockout relay R649 is completed at the armatures RA441 and RA471. At RA472, the relay R470 completes the above-traced alternative holding circuits for the relays R350 and R410. The relay R440, upon operating, completes its holding circuit and opens, at RA442, a point in the above-traced circuit for energizing the heating element 388 of the thermal relay 387 in parallel with the upper winding of the tone relay R340, thereby to prevent further deflection of the bimetallic strip 389 and to arrest the operation of the tone relay R340. At RA441 and its associated resting contact, the relay R440 opens a point in the initially completed holding circuit for the relay R410. The last-mentioned relay is, however, held operated over its alternative holding circuit as traced above. At RA443, the relay R449 prepares a circuit, traced hereinafter, for energizing the transfer relay R465. At RA445 and RA446, the relay R440 prepares a link connection between the calling line 18 and the called line to be selected. Following the operation of the four relays R330, R320, R470 and R440, the control apparatus of the link 16 is conditioned to respond to impulses transmitted thereto over the trunk line 13 from the operator's position 15.

From the foregoing description it will be apparent that the calling subscriber at the substation T₁ may initiate a call which is forwarded to the operator's position 15 by operating the hand generator 693 and without removing the receiver of the telephone instrument provided at the calling substation from its hook. If the call is initiated in this manner, the operator, upon answering the call and challenging the established connection, receives no response from the calling subscriber. If the calling subscriber fails to answer when the operator challenges the connection, the operator may recall the calling subscriber by operating the ringing key conventionally provided in her cord circuit, thereby to cause ringing current to be projected over the line conductors C385 and C386, through the repeating transformer 370, over the trunk line 13, through the repeating transformer 360, over the link line conductors C398, C399, C495 and C496, and out over the calling line 18 to energize the signal device provided at the calling substation T₁. A portion of this current is by-passed through the winding of the alternating current relay R450, which relay operates to open, at RA452, a point in the above-traced path for short-circuiting the lower winding of the line relay R680. Another portion of the ringing current is conducted through the upper winding of the line relay R680, causing this relay to operate and complete, at RA634, the previously described circuit for energizing its lower winding. When its lower winding is energized, the relay R680 fully operates to disconnect, at RA683, its upper winding from across the conductors C563 and C567 of the calling line 18. Thus, the impedance of this winding is removed from across the conductors of the calling line 18 and the major portion of the ringing current is conducted over the line to energize the signal device at the calling substation. At the end of the ringing operation and when the operator restores her ringing key to

disconnect the ringing current source from the line conductors C385 and C386, the alternating current relay R450 is deenergized and restores to recomplete, at RA452, the previously traced path for short-circuiting the lower winding of the line relay R680. As a result, this line relay again restores to connect its upper winding across the line conductors of the calling line 18.

When the calling subscriber at the substation T₁ removes his receiver from its hook in response to the calling operation just described, the desired conversational circuit is fully completed between the calling substation T₁ and the telephone set being used by the operator at the position 15. In this regard it is pointed out that transmission current is supplied to the loop extending between the calling substation T₁ and the repeater 360 from the local battery conventionally provided at the substation T₁. Transmission current for the loop extending from the operator's telephone set to the repeater 370 is derived from the exchange battery provided in the main exchange 9. Following the completion of the talking connection between the calling substation T₁ and the operator's telephone set in the manner just described, the operator may converse with the calling subscriber and ascertain the directory number of the desired substation or the name of the desired party.

If the call is to be forwarded to a substation associated with a line terminating at the main exchange 9, the operator may cause the desired connection to be set up in the manner conventionally employed in manual exchange practice.

Routing the call to a subscriber's line terminating at the tandem exchange

If the substation desired by the calling subscriber is associated with a subscriber's line terminating at the tandem exchange 10, the operator attending the position 15 operates the calling device 382 to dial the directory number of the called substation. For example, if the substation T₂ is the desired substation, the operator dials a single digit of four impulses, thereby to cause the wipers of the connector switch 550 to be moved into engagement with the contacts terminating the conductors of the line 19. More particularly, when the calling device 382 is operated, the above-described simplex operating circuit for the line relay R330 is interrupted a number of times at the pulsing springs 383 determined by the number of the dialed digit. Each time this circuit is opened, the line relay R330 restores to open, at RA331 and its associated working contact, the operating circuit for the hold relay R320 and to complete, at RA331 and its associated resting contact, the previously traced circuit for energizing the relay R455 in parallel with the connector switch operating magnet 540. The relay R455 operates at the beginning of the digit and, due to its slow-to-release characteristic, remains operated until shortly after the digit is ended. Since the hold relay R320 is also of the slow-acting type, this relay likewise remains operated throughout each pulsing period. When the relay R455 operates, it prepares, at RA456, the previously traced circuit for energizing the transfer relay R460 and opens, at RA457, a point in the path traced hereinafter for short-circuiting the holding winding of the combined line, cut-off and call storing relay associated with the line to be selected. At RA458, the relay R455 opens a point in the above-traced circuit for energizing the control relay R430. Each time

the operating magnet 540 of the connector switch 550 is energized and deenergized, the wipers of this switch are operated one step so that, at the conclusion of the digit, these wipers are left 5 standing in engagement with the contacts terminating the called line. In the present assumed case, wherein the directory number designating the called line 19 comprises four impulses, the magnet 540 is energized and deenergized four 10 times so that, at the conclusion of the digit, the wipers 551 to 554, inclusive, engage their respective associated fourth contacts. When these wipers are moved to their respective first off-normal positions, the off-normal springs 542 are 15 closed to prepare the previously traced circuit for energizing the relay R430.

At the end of the digit, the above-traced simplex circuit including the two conductors of the trunk line 13 is recompleted and the line relay 20 R399 remains in its operated position to hold open the above-traced circuit for energizing the magnet 540 and the relay R455 in parallel. Upon restoring, the relay R455 completes, at RA458, the 25 above-traced circuit for energizing the relay R430. At RA456, the relay R455 opens the prepared operating circuit for the relay R460 and, at RA457, prepares the above-mentioned path for short-circuiting the holding winding of the line relay associated with the called line 30 19. The relay R430, upon operating, completes, at RA435, its previously traced holding circuit and prepares, at RA433, a point in the previously traced alternative circuit for energizing the magnet 540 during the release of the connector switch 35 550. At RA432, the relay R430 prepares a circuit, traced hereinafter, for energizing the line switching relay R420. At RA431, the relay R430 prepares the operating circuit for the relay R460. Finally, at RA436 and RA437, the relay R430 40 completes a link connection between the calling line 18 and the called line 19.

Following the dialing operation, the operator supervising the call operates her ringing key to cause ringing current to again be projected over 45 the trunk line 13 and through the repeater 360. From this point on, the ringing current divides 50 between the calling and called lines, a portion of this current being projected through the operated armatures RA416 and RA417 of the relay R410 and the wipers 501 and 502 of the finder switch 500 out over the calling line 18, and another portion of the current being projected through the armatures RA445, RA446, RA436, RA437, RA422 and RA425 and the wipers 551 and 552 of the connector switch 550 out over the conductors of the called line 19. Another portion of the current is by-passed through the winding of the alternating current relay R450, which relay 55 operates to open, at RA451 and RA452, respectively, points in the above-described paths for short-circuiting the holding windings of the line relays respectively associated with the lines 19 and 18. A part of the ringing current conducted to the line 18 is by-passed through the upper winding of the line relay R680 with the result that this relay operates to complete the circuit for energizing its lower winding in series and then assumes its fully operated position to disconnect its upper winding from across the conductors of the line 18. In a similar manner, the line relay associated with the line 19 operates in response to the operation of the alternating current relay R450 to disconnect its operating winding from across the conductors of the called line 19. The ringing current projected over the 75

calling and called lines 18 and 19 serves to energize the ringers or signal devices respectively provided at the calling and called substations T₁ and T₂. In this connection, it is pointed out that, if the line 19 is of the multiparty type, such 5 that a number of substations are connected thereto, the operator actuates her ringing key in accordance with the code designating the desired substation T₂. Each time this key is restored to disconnect ringing current from the 10 trunk line 13, the relay R450 restores to recomplete, at RA451, the above-traced path for short-circuiting the lower winding of the line relay R680 associated with the calling line 18. Also, when the relay R450 restores it completes the 15 above-mentioned path for short-circuiting the holding winding of the line relay associated with the called line 19, this path extending from ground at RA457 by way of RA451, C485, the wiper 554, C594 and the holding winding of the 20 indicated line relay to ground. Conversely, each time the ringing key is operated to project ringing current over the trunk line 13, the relay R450 reoperates to open the above-described short-circuiting paths, thereby to permit the line relays 25 respectively associated with the calling and called lines fully to reoperate. At the end of the ringing operation, the alternating current relay R450 is deenergized and remains in its restored position. With this relay in its restored position, the holding winding of the line relay R680 is 30 short-circuited and the corresponding winding of the line relay associated with the called line 19 is also short-circuited. Accordingly, these 35 relays are caused to restore.

The desired conversational circuit between the calling and called substations is completed following the ringing operation and when the calling party removes the receiver of his telephone instrument from its supporting hook and the called party answers the call. It will be noted that the talking circuit thus established includes the finder switch wipers 501 and 502, the link line conductors C495 and C496, the operated armature springs of the three relays R410, R440 and 45 R430, the restored armature springs of the relay R420, the link line conductors C493 and C494, and the wipers 551 and 552 of the connector switch 550. Transmission current is supplied to the talking circuit from the local batteries conventionally provided at each of the two substations T₁ and T₂. Obviously, the operator attending the position 15 may continuously monitor the connection if she so desires. In any event, the calling key 380 is retained in its operated off-normal position until the connection is 50 ready to be released. The operator is expected to monitor the connection from time to time, for the purpose of ascertaining when the conversation is terminated in order that she may 55 initiate the release of the apparatus promptly following the end of the conversation.

Routing the call to a subscriber's line terminating at a subexchange

As indicated previously, calls initiated on lines terminating at the tandem exchange 10 may be routed, under the control of the operator attending the position 15, to any desired line terminating at either of the two subexchanges 11 and 12. In 70 this case, the operator, upon answering the call and ascertaining the substation desired by the calling subscriber, dials the two digits of the directory number designating the desired line, the impulses of the first digit being utilized to cause 75

the connector switch 550 to position its wipers on the contacts terminating the trunk line extending to the particular subexchange terminating the desired line, and the impulses of the second digit being routed through the control apparatus of the link 16 to the control apparatus of the link provided in the selected exchange to cause the connector switch of the selected exchange to select the desired line. For example, if the call initiated at the substation T_1 and routed to the operator's position 15 in the main exchange 9 is intended for the substation T_4 associated with the line 22 terminating at the subexchange 11, the operator dials the two digits of the directory number designating the line 22. In this assumed case, the first digit dialed by the operator comprises a single impulse so that, at the conclusion thereof, the wipers of the connector switch 550 are positioned in engagement with their respective associated first contacts. Shortly following the end of this digit and when the slow-to-release relay R455 restores, in the manner explained above, it completes, at RA458, the previously traced operating circuit for the relay R430, causing the last-mentioned relay to operate to perform the line switching and control functions described previously. On this type of call, namely, a trunk call, the relay R430 also completes a circuit for energizing the line switching and control relay R420 in series with the line switching relay R610 embodied in the line circuit associated with the selected trunk line 14. This circuit may be traced as extending from ground by way of the winding of R420, RA432, RC469, RA468, C487, the wiper 553 and its associated first contact, C591 in the cable 560, and the winding of R610 to battery. Both of the relays R420 and R610 operate, when energized over this circuit. The relay R420, upon operating, prepares at its four armatures RA421, RA422, RA424 and RA425 a simplex pulsing circuit which includes the two conductors of the trunk line 14 and extends through the winding of the line relay R740 provided in the link 21. This pulsing circuit is completed at the armatures RA612, RA613, RA615 and RA616 when the relay R610 operates. At RA613 and RC614, the relay R610 opens the original energizing circuit for the line relay R740 following the completion of the simplex pulsing circuit just mentioned. At RA611 and RA616, the relay R610 disconnects the conductors of the trunk line 14 from the line conductors C565 and C561 extending to the contacts of the finder switch 500. The above-mentioned simplex pulsing circuit, which is completed in response to the operation of the two relays R420 and R610, may be traced as extending from battery by way of the resistor 333 and RA332 to C397 where it divides, one branch extending by way of RA421, RA422, C493, the wiper 552, C585, RA612, RA613, C767, RA764, the winding 752 and the winding of the line relay R740 to ground, and the other branch extending by way of RA424, RA425, C494, the wiper 551, C581, RA615, RA616, C766, RA763, 65 the winding 751 and the winding of R740 to ground. Following the completion of this circuit, the control apparatus of the two links 16 and 21 is conditioned to respond to the impulses of the second digit designating the particular desired line terminating at the subexchange 11. At the beginning of the first impulse of the second digit, the operating circuit for the relay R455 is again completed, it being observed that, due to the energized condition of the relay R430, 75 the operating circuit for the connector switch

magnet 540 is now open at RA434. Upon operating, the relay R455 completes, at RA456, the previously mentioned circuit for energizing the digit transfer relay R460, this circuit extending from ground at RA431 by way of RA456, RA466 5 and the winding of R460 to battery. The relay R460, upon operating, completes a path for short-circuiting the winding of the relay R465, this path extending from ground by way of the off-normal springs 542, C490, RA443, RA461, the 10 winding of R465, RA466, RA456, and RA431 to ground. Due to its slow-to-release characteristic, the relay R455 remains operated throughout the second series of impulses to maintain this short-circuiting path completed. During each 15 impulse of the second digit, the line relay R330 alternately restores and reoperates, thereby to open and complete, at RA332, a point in the previously traced simplex pulsing circuit which extends through the winding of the line relay 20 R740. Thus, the impulses of the second digit are repeated to the line relay R740 of the link 21 through the operation of the control apparatus embodied in the link 16. The line relay R740 follows the pulses and 25 causes the connector switch 850 to position its wipers on the contacts terminating the conductors of the desired called line. More particularly, at the beginning of the first impulse, when the line relay R740 restores, it completes, at 30 RA474, the previously traced circuit for energizing the slow-to-release relay R830 in parallel with the connector switch operating magnet 818. The relay R830 operates, when it is first energized and, due to its slow-to-release characteristic, remains operated throughout the pulsing period. At RA831, the relay R830, upon operating, opens a point in the path, traced herein-after, for short-circuiting the holding winding of the line relay R700 associated with the called 40 line 22. At RA832, the relay R830 opens a point in the connection between the repeating transformer 750 and the line wiper 852 of the connector switch 850, thereby to prevent interference with conversations ensuing on subscribers' lines 45 occupied with reverting calls. In the present case, the conductors of the called line are terminated at the respective first contacts of the connector switch contact bank and, accordingly, the second digit dialed at the operator's position 15 50 will necessarily comprise a single impulse so that, at the end of the digit, the wipers of the switch 850 are left standing in engagement with their respective associated first contacts. When these wipers are moved to their respective first off-normal positions, the off-normal springs 827 are closed to prepare the previously traced circuit for energizing the operating magnet 818 during the release of the connector switch. Shortly following the end of the second digit and with the line 60 relay R740 in its operated position, the slow-to-release relay R330 restores to connect, at RA832, the line wiper 852 to the link line conductor C863 and to prepare, at RA834, the above-mentioned path for short-circuiting the holding winding of 65 the line relay R700.

At the end of the second digit and with the line relay R330 of the link 16 in its operated position, the operating circuit for the slow-to-release relay R455 is held open at the armature 70 RA331. As a result, the relay R455 restores shortly following the end of the second digit to open, at RA456, a point in the above-traced path short-circuiting the winding of the relay R465. The winding of the last-mentioned relay is now 75

energized in series with the winding of the relay R460 over a circuit which extends from ground by way of the off-normal springs 542, C499, RA443, RA461 and the series connected windings of the relays R465 and R460 to battery. The relay R460 remains in its operated position and the relay R465 operates when the above-traced short-circuiting path is interrupted and the series circuit, just traced, is established. Upon operating, the relay R465 opens, at RA466, a further point in the operating circuit for the relay R460 as well as a further point in the above-traced path for short-circuiting its own winding. At RA467 and RA468, the relay R465 completes an alternative circuit for energizing the switching relay R310, this alternative circuit extending from ground at RA473 by way of RA467, RA468, C487, the wiper 553, C591 and the winding of R610 to battery. Thereafter, the relay R465 opens, at RA468 and RC469, a point in the above-traced circuit for energizing the relays R420 and R610 in series. The relay R420 is now deenergized and restores to complete, at RA422 and RA425 and their respective associated contacts RC423 and RC426, an alternative simplex circuit for maintaining the line relay R740 of the link 21 energized. One branch of this alternative simplex circuit may be traced as extending from battery by way of the winding of the impedance element 365, the winding 363, C398, RA446, RA437, RC428, RA425, C494, the wiper 551, C581, RA615, RA616, C766, RA763, the winding 751 and the winding of the relay R740 to ground. The other branch of this circuit extends from battery through the winding of the impedance element 365 and by way of the winding 364, C399, RA445, RA436, RC423, RA422, C493, the wiper 552, C585, RA612, RA613, C767, RA764, the winding 752 and the winding of R740 to battery. After the completion of this simplex circuit the original simplex circuit extending by way of the resistor 383 is interrupted at the armatures RA421, RA422, RA424 and RA425 during the restoration of the relay R420. Following the restoration of the relay R420 in the manner just described, the desired connection is fully completed between the calling and called lines 18 and 22 respectively, and also between each of these two lines and the operator's position 15 in the main exchange 9. To signal the calling and called subscribers, the operator supervising the call at the operator's position 15 actuates her ringing key to cause ringing current to be projected over the established connection and the calling and called lines to energize the signal devices respectively provided at the calling and called substations. Here again, if the called substation is associated with a line of the multi-party type, coded ringing may be utilized to signal the desired substation. Each time the ringing current source is connected across the line conductors C385 and C386, ringing current is projected over the trunk line 13 and through the repeater 369 to the link line C398, C399. A portion of this current is transmitted back over the calling line to energize the signal device provided at the calling substation, thereby to signal the calling subscriber that the called substation is being rung. In addition, the alternating current relay R450 is caused to operate at the beginning of each ringing period and to restore at the end of each ringing period to perform the control functions previously described with reference to the call routed to the substation T₂. During each ringing interval, a further portion of the

ringing current is transmitted over the trunk line 14, through the repeater 750, over the link line conductors C383 and C385, and out over the called line 22 to energize the signal device provided at the substation T₄. A part of this ringing current is shunted through the winding of the alternating current relay R730, causing this relay to operate and open, at RA731, a point in the above-mentioned path for short-circuiting the holding winding of the line relay R700. During the initial part of each ringing period a part of the ringing current which is conducted over the line 22 is shunted through the upper winding of the line relay R700, causing this relay to operate to complete at RA702, a circuit including the resistor 735 for energizing its lower winding. Thus, during each ringing interval, the relay R700 is fully operated so that its upper winding is disconnected at RA701 from across the conductors of the line 22. Accordingly, this winding is prevented from shunting the ringing current away from the signal device provided at the called substation T₄. At the end of each ringing interval, the alternating current relay R730 is deenergized and restores to complete, at RA731, the above-mentioned path for short-circuiting the lower winding of the relay R700, this short-circuiting path extending from ground at RA731 by way of C346, RA831, the wiper 853, C844, the lower winding of R700 and RA702 to ground. As a result, the relay R700 restores to reconnect, at RA701, its upper winding across the conductors of the line 22. The desired conversational circuit between the calling and called substations is completed following the ringing operation and when the calling party removes the receiver of his telephone instrument from its supporting hook and the call is answered at the called substation T₄. In this regard, it is pointed out that transmission current is supplied to the loop extending between the called substation T₄ and the repeater 750 from the local battery conventionally provided at the indicated substation. Transmission current is similarly supplied to the loop extending between the calling substation T₁ and the repeater 750 from the local battery provided at the substation T₁. Here again, the operator attending the operator's position 15 in the central exchange 9 may continuously monitor the connection if she so desires. Alternatively, she may monitor the connection at intervals to determine when the connection is ready to be released. In any case, the calling key 380 is held in its off-normal position to hold the switch train operated until the operator ascertains that the connection is no longer desired.

Reverting call on a subscriber's line extending to the tandem exchange

If the call, as forwarded to the operator's position 15 from the substation T₁, is intended for another substation associated with the calling line 18, the only operation performed by the operator is that of actuating her ringing key in accordance with the coded ring designating the desired substation, thereby to energize the signaling devices individually provided at the substations associated with this line. The coded character of the ringing indicates to the called subscriber that his substation is being rung and to the calling subscriber that the ringing operation is in progress. After the ringing operation is terminated and the calling and called subscribers operate their receivers to connect the telephone instruments, respectively provided at

the calling and called substations to the line 18. the desired conversational circuit is fully completed. On this type of call, only the line extending between the two substations is utilized 5 in the connection. Accordingly, the operator attending the position 15 may release the operated link 16 immediately the ringing operation is completed, thereby to render the automatic switching apparatus provided in the three exchanges 10, 11 and 12 available for further use. In this 10 regard, it will be noted that no provision is made for guarding the line 18 against seizure while the conversation being held thereover is in progress. No interference with the conversation will result, however, if the operator in the exchange 15 monitors each established connection after completing a dialing operation and before starting the ringing operation. On a call of this character, the calling and called subscribers are not 20 expected to "ring off" at the end of the conversation since operation of either of the two generators respectively provided at the calling and called substations would result in seizure of the link 16 in the manner previously explained. 25 It will be apparent that a call between two substations connected to the same subscribers' line may be completed without the assistance of the operator attending the operator's position 15 in the main exchange 9. For example, if the calling 30 subscriber at the substation T₁ desires a connection with a second substation connected to the line 18, the desired substation may be signaled directly by operating the hand generator 693 in accordance with the coded ring designating 35 the desired substation. In such case, however, the call is forwarded to the operator's position 15 in the manner explained previously, assuming that the automatic switching apparatus provided in the three exchanges 10, 11 and 12 is 40 idle at the time the call is initiated. If the automatic switching apparatus is busy, the call is stored by the line relay R680 and is thereafter forwarded to the operator's position, in the manner subsequently explained, when the apparatus 45 becomes idle. If a reverting call is completed in this manner, the operator, upon answering the call as forwarded to the operator's position 15, may release the operated switching apparatus without performing any service whatever.

50 *Release of the automatic switching apparatus*

When the conversation being held over a connection including two of the subscribers' lines extending to the exchanges 10, 11 and 12 is 55 ended, one of the two subscribers utilizing the connection is expected to "ring off" in order to transmit a disconnect signal to the operator attending the position 15. For example, the calling subscriber at the substation T₁ may operate 60 the hand generator 693 for a short time interval to cause ringing current to be projected over the established connection to the operator's position 15, thereby to energize the receiver of the operator's telephone set so that the operator is 65 signaled that the connection is ready to be released. When the hand generator 693 is operated for this purpose, the upper winding of the line relay R680 is energized by the ringing current, and the alternating current relay R459 70 bridging the connection is also energized and operates. In addition, a portion of the ringing current is conducted over the established connection and through the operating winding of the line relay associated with the called line. 75 Thus, if the established connection extends be-

tween the lines 18 and 19, the operating winding of the line relay embodied in the line circuit 690 is energized by the ringing current and operates. When the relay R459 operates, it opens, at its armatures RA451 and RA452, points in the above-traced paths for respectively short-circuiting the holding windings of the respective line relays associated with the calling and called lines. As a result, the respective holding windings of the two line relays individually associated with the 10 calling and called lines are energized in series, and the respective operating windings of these relays are disconnected from across the conductors of the respective associated lines.

If the established connection extends between 15 the line 18 and the line 22 terminating at the subexchange 11, a portion of the ringing current is projected over the established connection and divides between the alternating current relay R730, the upper or operating winding of the 20 line relay R700 and the signal device provided at the called substation. As a result, the two relays R700 and R730 operate. The relay R730, upon operating, opens, at RA131, a point in the path for short-circuiting the lower winding of the 25 relay R700, permitting the lower winding of this relay to be energized so that the upper winding of the relay is disconnected from across the conductors of the line 22 during the period when the generator 693 is being operated. When 30 the operation of the generator 693 is arrested, the relay R459 restores to short-circuit the holding winding of the line relay R680 over the path traced previously, whereby this relay is caused 35 to restore. Also, if the established connection includes the line 19, the holding winding of the line relay embodied in the line circuit 690 is also short-circuited and restores. Alternatively, if the connection extends between the lines 18 and 22, the relay R730 restores at the end of the 40 "ring-off" period to complete, at RA731, the previously traced path for short-circuiting the lower winding of R700, causing the last-mentioned relay to restore and reconnect its upper winding 45 across the conductors of the line 22. The relay operations just described occur during and following the "ring-off" period, irrespective of whether the calling or the called party operates his hand generator to transmit the "ring off" or disconnect signal to the operator.

50 When the operator attending the operator's position 15 receives the disconnect signal or, alternatively, challenges the established connection and finds that the connection is no longer being used, she may initiate the release of the 55 operated switching apparatus by restoring the calling key 380 to its normal position. When this key is returned to its normal position, the switch springs 376 and 377 are closed to reconnect the winding of the drop 375 across the conductors 60 C367 and C368 of the trunk line 13. At the switch springs 371, 378, 379 and 381, the above-traced simplex operating circuit for the line relay R330 is interrupted. The line relay R330, upon restoring, opens, at RA331, the operating 65 circuit for the hold relay R320, thereby to cause the sequential restoration of this relay and the relay R470 in the order named. Upon restoring, the line relay R330 completes, at RA331, the previously traced operating circuit for the slow-to-release relay R455. Shortly thereafter and when the relay R470 restores, this circuit is interrupted at RA471. The momentary reoperation of the relay R455 is without effect at this time. When the relay R470 restores, it completes, at RA471, 70 75

the previously traced circuit for energizing the pendulum type relay R480. Thus, vibration of the weighted armature RA481 is initiated. During each vibration of this armature the operating circuit for the relay R310 is completed but, due to the slow-to-operate characteristic of this relay, it remains in its restored position until after the armature RA481 settles into resting engagement with its associated grounded contact. The relay R470, upon restoring, also interrupts, at RA472, a point in the common portion of the previously traced holding circuits for the two relays R410 and R350, causing both of these relays to restore. At RA473, the relay R470 opens a point in the above-traced holding circuit for the switching relay R819 embodied in the line circuit associated with the trunk line 14, causing the last-mentioned relay to restore, if operated. At RA471 and its associated working contact, the relay R470 interrupts the previously traced multiple holding circuit for the lockout relay R640. At RA475, the relay R470 interrupts the operating circuit for the control and line switching relay R440.

The relay R350, upon restoring, opens, at RA351 and RA352, a further point in the above-traced alternative holding circuit for the relay R410 and reprepares, at RA352 and RC353, the operating circuit for the relay R355. The relay R410, upon restoring, opens, at RA415, a further point in the common portion of its two locking circuits as traced above and, at RA414, a point in the previously traced path for short-circuiting the lower winding of the line relay R680 associated with the calling line 18. At RA413 and its associated resting contact, the relay R410 reprepares the previously traced operating circuit for the finder switch start relay R520. At RA411 and its associated working contact, the relay R410 interrupts the remaining holding circuit for the lockout relay R640, causing the last-mentioned relay to restore. At RA411 and its associated resting contact, the relay R410 reprepares the operating circuit for the finder switch operating magnet 530. Finally, at RA416 and RA417, the relay R410, upon restoring, opens two points in the established talking connection and two points in the previously traced simplex circuit extending by way of the trunk line 14 for energizing the line relay R740 of the link 21.

When the vibratory movement of the pendulum relay armature RA481 is ended, the slow-to-operate relay R310 is continuously energized and operates to open, at RA311, the holding circuit for the relay R440, causing the last-mentioned relay to restore and open, at RA445 and RA446, two additional points in the link connection extending between the calling and called substations. At RA444, the relay R440 opens a further point in its own holding circuit. At RA441, the relay R440 interrupts the previously traced operating circuit for the pendulum relay R480, causing the sequential restoration of this relay and the slow-to-operate relay R310. At RA442, the relay R440 reprepares a further point in the previously traced circuit for energizing the finder switch start relay R520. At RA443 and its associated working contact, the relay R440 interrupts the above-traced circuit for energizing the two relays R460 and R465 in series, causing both of these relays to restore, if operated. At RA443 and its associated resting contact, the relay R440 completes the previously traced circuit for energizing the operating magnet 540 of the connector switch

550 by way of the circuit interrupting contacts associated with the armature 541. When this last-mentioned circuit is completed, the magnet 540 operates, buzzer fashion, to drive the wipers of the switch 550 to their respective home positions, at which time the off-normal springs 542 are disengaged. When these springs are opened, the holding circuit for the relay R430 is interrupted, causing this relay to restore to interrupt, at RA433, the release circuit for the operating magnet 540. As a result, the stepping operation of the connector switch 550 is arrested. Following the restoration of the relay R430, the link 16 is fully released.

If the established connection extends between two subscribers' lines terminating at the tandem exchange 10 the release of the apparatus embodied in the finder connector links 21 and 25 is initiated when the lockout relay R640 restores. More particularly, when this relay restores it removes negative battery potential from the conductors C767 and C604 of the trunk lines 14 and 17, respectively. When negative battery potential is removed from the conductor C767 the link 21 is released in the manner previously explained with reference to the release operations initiated through operation of the thermal relay 387. The link 25 is similarly released when negative battery potential is removed from the conductor C604 of the trunk line 17.

If the established connection extends to a subscriber's line terminating at the subexchange 11, the release of the operated switching apparatus in this exchange is initiated in response to the interruption of the simplex circuit extending over the trunk line 14 between the exchanges 10 and 11 and including the winding of the line relay R740. When this circuit is opened, the line relay R740 is deenergized and restores to open, at RA741, the operating circuit for the hold relay R735 and to recomplete the previously traced operating circuit for the slow-to-release relay R830. Thereafter and when the hold relay R735 restores, it opens, at RA738, the completed circuit for energizing the relay R830. The momentary reoperation of the last-mentioned relay is without effect at this time. Upon restoring, the relay R735 also opens, at RA731, the operating circuit for the relay R710 and interrupts, at RA736 and its associated working contact, the operating circuit for the relay R755, causing both of these relays to restore. At RA736 and its associated resting contact, the relay R735 completes the previously traced circuit for energizing the connector switch operating magnet 818 by way of the armature 819. Due to the circuit interruption action of the springs controlled by the armature 819, the magnet 818 operates, buzzer fashion, to drive the wipers of the switch 850 to their respective home positions, at which time the off-normal springs 827 are opened to arrest the operation of the magnet 818. Following the last-mentioned operation, the control apparatus embodied in the link 21 is fully released. It will be understood that in this case the release of the link 25 provided in the subexchange 12 is initiated when the lockout relay R640 restores to remove negative battery potential from the conductor C604 of the trunk line 17 and is accomplished in the exact manner described above.

Call initiated on a subscriber's line extending to a subexchange

As indicated previously, calls originating on the subscribers' lines terminating at the subex-

changes are forwarded to the operator's position 15, from which point they may be routed to the desired substations under the control of the operator attending this position. For example, if 5 a subscriber at the substation T₄ operates the hand generator 775 to initiate a call at a time when the automatic switching apparatus provided in the three exchanges 10, 11 and 12 is idle, the line relay R₇₀₀ operates to initiate the 10 operation of the finder switch 800. More particularly, when the generator 775 is operated, the upper winding of the relay R₇₀₀ is energized over a circuit extending from one terminal of the generator 775 by way of the springs 778, C₈₄₁, 15 the upper winding of R₇₀₀, RA₇₀₁ and C₈₄₂ to the opposite terminal of the generator 775. When energized over this circuit, the relay R₇₀₀ operates to close the "X" contacts associated with RA₇₀₂, thereby to complete an obvious circuit 20 for energizing the lower winding of R₇₀₀. Thereafter, the relay R₇₀₀ opens, at RA₇₀₄, a point in its primary operating circuit and completes, at RA₇₀₃, a path extending by way of C₈₄₃ for marking the calling line 22 in the bank contacts of the finder switch 800. At RA₇₀₄, the relay R₇₀₀, upon fully operating, completes a circuit 25 for energizing the finder switch start relay R₈₂₅, this circuit extending from ground at RA₇₂₁ by way of RA₇₀₄, C₈₄₈ and the winding of R₈₂₅ to battery. The start relay R₈₂₅, upon operating, completes, at RA₈₂₆, a circuit for energizing the operating magnet 816 of the finder switch 800, which circuit may be traced as extending from ground at RA₇₂₁ by way of RA₇₅₉, 30 C₈₆₂, RA₈₂₆, RA₈₂₁ and the winding of the magnet 816 to battery. When energized over this circuit, the magnet 816 operates to condition the associated ratchet and pawl mechanism to step the wipers of the switch 800 one step and completes, at its armature 817, an obvious circuit 35 for energizing the upper winding of the pulsing relay R₈₂₀. The last-mentioned relay, upon operating, opens, at RA₈₂₁, a point in the operating circuit for the magnet 816, whereby this magnet 40 is deenergized and the wipers of the switch 800 are stepped one step. Also, upon deenergization of the magnet 816, the operating circuit for the pulsing relay R₈₂₀ is interrupted at the armature 817, causing this relay to restore to recomplete 45 the operating circuit for the magnet 816. The inter-related operation of the magnet 816 and the pulsing relay R₈₂₀ continues until the wipers of the finder switch 800 are positioned on the contacts terminating the conductors of the calling 50 line 22. More particularly, when the wiper 803 is driven into engagement with its associated first contact, a circuit is completed for energizing the respective lower windings of the two relays R₈₂₀ and R₇₂₀ in series, this circuit extending by way 55 of the grounded marking conductor C₈₄₃, the first contact of the set 807, the wiper 803, C₈₆₁, RA₇₅₈, the lower winding of R₇₂₀, C₈₆₀ and the lower winding of R₈₂₀ to battery. When this circuit is completed, the relay R₈₂₀ remains operated independently of the condition of the magnet 816 and, accordingly, the stepping operation of the finder switch 800 is arrested. The line test relay R₇₂₀ operates, when its lower winding is energized over the test circuit just 60 traced and, upon operating, completes, at RA₇₂₄, an obvious locking circuit for itself. At RA₇₂₃, the relay R₇₂₀ prepares an alternative holding circuit for itself and in so doing completes a circuit for energizing the slow-to-release relay R₇₆₀, 65 which latter circuit may be traced as extending

from ground at RA₇₁₃ by way of RA₇₂₃, RA₇₅₇, and the winding of R₇₆₀ to battery. At RA₇₂₁ and its associated resting contact, the relay R₇₂₀ opens a point in the common portion of the operating circuits for the magnet 816 and the relay 5 R₉₂₅. The relay R₈₂₅ now restores to open, at RA₈₂₆, a further point in the operating circuit for the magnet 816. At RA₇₂₂, the relay R₇₂₀ completes a path for short-circuiting the lower winding of the line relay R₇₀₀ associated with 10 the calling line 22, this circuit extending from ground at RA₇₃₁ by way of RA₇₂₂, C₈₄₅, the wiper 804 and its associated first contact, C₈₄₄, the lower winding of R₇₀₀ and RA₇₀₂ to ground. 15 When this path is completed, the relay R₇₀₀ restores to reconnect its upper or operating winding across the conductors of the line 22. At RA₇₂₁ and its associated working contact, the relay R₇₂₀ completes a circuit for energizing the upper winding of the tone relay R₇₄₅. This circuit 20 may be traced as extending from ground at RA₇₂₁ by way of RA₇₁₁, the upper winding of R₇₄₅ and the resistor 747 to battery. At its two lower armatures RA₇₂₅ and RA₇₂₆, the line test relay R₇₂₀ connects the link line conductors 25 C₈₆₄ and C₈₆₆ to the line terminals of the repeater 750, thereby to complete a connection between the calling substation and the indicated repeater. 30

When the upper winding of the tone relay R₇₄₅ is energized over the circuit traced above, it operates to short-circuit, at RA₇₄₆, its upper winding and immediately restores. Thus, this relay operates in the manner of a buzzer and, due 35 to the alternate energization and deenergization of its upper winding, causes an induced voltage to be developed in its lower winding which is impressed through the condenser 748 across the line conductors of the calling line. As a result, a waiting tone signal is transmitted to the calling 40 subscriber to indicate that the automatic switching apparatus is idle and has been seized.

The slow-to-release relay R₇₆₀, upon operating, connects the terminals of the battery provided in the exchange 11 to the line conductors of 45 the trunk line 14 and, in so doing, completes a circuit for energizing the lower winding of the line relay R₆₃₀ associated with the trunk line 14 in the tandem exchange 10. More particularly, this circuit may be traced as extending from 50 ground by way of RA₇₆₄, C₇₆₇, RA₆₁₃, RC₆₁₄, RA₆₂₁, RA₆₄₃, the lower winding of R₆₃₀, C₇₆₆, RA₆₃₃ and the resistor 762 to battery. When its lower winding is energized over this circuit, the relay R₆₃₀ operates to complete, at RA₆₃₃, a 55 holding circuit for itself, this circuit including the upper winding of R₆₃₀ and extending from ground at RA₆₄₄. The line relay R₆₃₀, upon operating, also initiates the operation of the finder switch 500 to find the calling trunk line 14, in the 60 manner subsequently explained.

The relay R₇₆₀, upon operating, also completes, at RA₇₆₁, an obvious circuit for energizing the relay R₇₅₅, which latter relay, in turn, operates to complete a holding circuit for itself. 65 This holding circuit may be traced as extending from ground at RA₇₁₃ by way of RA₇₂₃, RA₇₅₇, RA₇₅₆ and the winding of R₇₅₅ to battery. At RA₇₅₇ and its associated resting contact, the relay R₇₅₅ interrupts the previously traced operating 70 circuit for the slow-to-release relay R₇₆₀, causing the latter relay to restore after an interval to open, at RA₇₆₃ and RA₇₆₄, two points in the above-traced operating circuit for the line relay R₆₃₀. At these same armatures and their 75

respective associated back contacts, the relay R760 reconnects the line conductors of the trunk line 14 to the line terminals of the repeater 750, thereby to extend the connection from the calling line 22 to the automatic switching apparatus provided in the tandem exchange 10. At RA761, the relay R760, upon restoring, opens a point in the operating circuit for the relay R755. The relay R755, upon operating, also opens, at RA758, a point in the series circuit including the respective lower windings of the line test relay R720 and the finder pulsing relay R820, causing the last-mentioned relay to restore. At RA759, the relay R755 opens a further point in the operating circuit for the finder switch operating magnet 816. The line relay R630, upon operating in the manner explained above, completes, at RA632, a path for marking the calling trunk line 14 in the bank contacts of the finder switch 500, this path extending from ground at RA457 by way of RA451, C485, the wiper 554 and its associated home contact, C483, RA442, RA413, C484, RA632 and C571 to the first contact of the contact set 507. At RA631, the relay R630 completes a circuit for energizing the finder start relay R523, this circuit extending from ground at RA631 by way of C484' and the winding of R520 to battery. Upon operating, the relay R520 completes, at RA521, the previously traced operating circuit for the operating magnet 530, thereby to initiate the inter-related operation of this magnet and the pulsing relay R510 in the manner previously explained. Through the interrelated operation of the magnet 530 and the relay R510, the wipers of the finder switch 500 are stepped over the contacts of their respective associated contact sets until the calling trunk line 14 is found. When the calling line is found, the line test relay R410 is energized in the manner explained above and, upon operating, performs the previously explained functions. In addition, this relay completes, at RA414, a circuit for energizing the slow-to-operate cut-off relay R620, this circuit extending from ground at RA452 by way of RA414, C491, the wiper 504 and its associated first contact, C575 and the winding of R620 to battery. Upon operating, the relay R620 completes, at RA622, a holding circuit for itself, this circuit extending from ground at the now operated armature RA644 of the lockout relay R640 by way of RA622 and the winding of R820 to battery. At RA621, the relay R620 disconnects the lower winding of the line relay R630 from across the line conductors of the trunk line 14. At this same armature, the relay R620 opens a point in the previously traced circuit for energizing the line relay R740 from battery as connected to the resistor 646. When the lockout relay R640 operates, it opens, at RA644, a point in the holding circuit for the line relay R630, causing the last-mentioned relay to restore to interrupt, at RA631, the above-traced operating circuit for the finder switch start relay R520. Upon restoring, the relay R520 opens, at RA521, a further point in the operating circuit for the magnet 530 and opens, at RA522, a further point in the above-traced circuit for energizing the lower winding of R510 in series with the upper winding of the relay R410. The pulsing relay R510 now restores. From this point on, the manner in which the control apparatus of the link 16 operates to forward the call to the operator's position 15 in the main exchange 9 is exactly the same as previously explained with reference to the call initiated at the substation T₁.

During the sequence of operations just described and when the lockout relay R640 operates, the previously traced circuit including the resistor 646 is completed for energizing the line relay R740 embodied in the link 21. Also, negative 5 battery potential is impressed upon the line conductor C504 of the trunk line 17 to cause the operation of the control apparatus of the link 23, whereby the finder portion of this link is rendered nonresponsive to calls initiated on the 10 subscribers' lines terminating at the exchange 12.

When the line test relay R410 operates, a simplex circuit is also completed for energizing the line relay R740 embodied in the link 21, one branch of this circuit extending from ground by way of the winding of R740, the winding 752, RA754, C767, RA611, C565, the wiper 582, C495, RA416, C393, the winding 363 and the winding of the impedance element 365 to battery. The other branch of this simplex circuit extends from 15 ground by way of the winding of R740, the winding 751, RA753, C766, RA616, RC617, C561, the wiper 581, C496, RA417, C399, the winding 364 and the winding of the impedance element 365 to battery. When energized over the circuits described above, the line relay R740 operates to cause the sequential operation of the hold relay R735 and the slow-to-release control relay R710 in the order named. The hold relay R735, upon operating, completes, at RA736, alternative holding circuits for each of the two relays R720 and R755, the holding circuit for the relay R755 extending from ground at RA736 by way of the winding of R755 to battery, and the holding circuit for the relay R720 extending from ground at RA736 by way of RA756, RA757, RA723, RA724 and the upper winding of R720 to battery. When the control relay R710 operates, it opens, at RA712, a point in the common portion of the initially completed holding circuits for the relays 20 R720 and R755 and opens, at RA711, a point in the previously traced circuit for energizing the upper winding of the tone relay R745. Thus, the operation of the tone relay R745 is arrested. Following the operation of the relay R710, no 25 further operation of the control apparatus embodied in the link 21 occurs until the call is answered at the operator's position 15 and a ringing or dialing operation is performed by the operator attending this position. 30

In the event the operator attending the position 15 fails to answer the call within a reasonable length of time, the thermal timing relay 387 operates to initiate the release of the link 16 in the manner set forth above with reference 35 to the call initiated at the substation T₁. During the release of the link, the cut-off relay R620 is deenergized and restores in response to the restoration of the lockout relay R640 to open its holding circuit at RA644. During the release of 40 the link 16, the line test relay R410 also restores to open, at its armatures RA416 and RA417, the above-traced simplex operating circuit for the line relay R740 of the link 21. When this simplex circuit is interrupted, the line relay R740 is 45 deenergized and restores to cause the sequential restoration of this relay and the two relays R735 and R710 in the order named. Immediately the relay R740 falls back, it completes, at RA741, the previously traced circuit for energizing the relay R830 and the operating magnet 818 in parallel. This circuit is interrupted shortly thereafter in response to the restoration of the hold relay R735. Thus, a pulse is delivered to the operating magnet 818, and the relay R830 is 50

75

momentarily operated. The momentary operation of the relay R830 is without effect, but the energizing pulse delivered to the magnet 818 causes the wipers of the connector switch 850 to be stepped to their respective first off-normal positions, thereby to close the off-normal springs 827. When these springs are closed, the previously traced circuit for energizing the relay R830 and the magnet 818 by way of the circuit interrupting contacts controlled by the armature 819 is completed. As a result, the magnet 818 operates, buzzer fashion, to drive the wipers of the switch 850 to their respective home positions, at which time the off-normal springs 827 are opened to interrupt the circuit for energizing the relay R830 and the magnet 818. Thus, operation of the connector switch is arrested and the relay R830 is caused to restore. When the hold relay R735 restores, it opens, at RA736, a point in the common portion of the above-traced alternative holding circuits for the two relays R720 and R755, causing both of these relays to restore. Shortly thereafter, the relay R710 restores to reprepare the original holding circuits for these two relays. Following the operation of the magnet 818 to drive the wipers of the connector switch 850 to normal, the link 21 is fully released.

30 *Routing the call to a subscriber's line extending to the tandem exchange*

If the call as forwarded to the operator's position 15 is answered, by operation of the calling key 380 to its off-normal position, before the thermal relay 387 operates to initiate the release of the switching apparatus, the four relays R330, R320, R470 and R440 are caused sequentially to operate, in the order named and in the manner previously explained. The relay R440, upon operating, opens, at RA442, a point in the previously traced circuit for energizing the upper winding of the tone relay R340 in parallel with the heating element 388 of the thermal relay 387, thereby to arrest the operation of the tone relay 45 and to deenergize the heating element. As a result, operation of the thermal relay 387 is arrested before release of the automatic switching apparatus is effected in the manner just explained. If, upon answering the call and challenging the connection, the operator receives no response, she may operate the ringing key provided in her cord circuit to cause ringing current to be projected back over the established connection for the purpose of energizing the signal device provided at the calling substation T4. When ringing current is transmitted over the established connection, the two alternating current relays R730 and R450 are energized and operate. The operation of the relay R450 is without effect, 60 however. When the relay R730 operates, it functions to open, at RA731, a point in the previously traced path for short-circuiting the lower winding of the line relay R700 associated with the calling line 22. Hence, when the upper winding of the line relay R700 is energized by the ringing current transmitted therethrough from the ringing current source provided in the exchange 9, it operates to complete the previously described circuit for energizing its lower winding. As a result, the relay R700 remains in its fully operated position throughout the ringing operation so that its upper winding is disconnected from across the conductors of the calling line and the ringing current is not shunted away from the signal device provided at the

calling substation. The relays R450, R730 and R700 restore in an obvious manner when the ringing operation is ended. When the calling subscriber answers the call, he may converse with the operator attending the position 15 and instruct the operator as to the particular substation desired. If the call is to be routed to a line terminating at the main exchange 9, the operator may extend the connection to the desired substation in the manner conventionally employed in manual office practice. On the other hand, if the connection is to be routed to a substation associated with a line terminating at the tandem exchange 10, such, for example, as the substation T2, the desired connection may be set up under the control of the operator in the exchange 9 in the exact manner described previously with reference to the call initiated at the substation T1. After the connection is fully established, the operator retains the calling key 380 in its off-normal position to hold the automatic switching apparatus operated. At the end of the conversation and when the disconnect signal is received by the operator, she may initiate the release of the apparatus by restoring the calling key 380 to its normal position, it being pointed out that the two links 16 and 21 are released in the exact manner previously described. In this case, however, the release of the link 21 is initiated in response to the restoration of the link 30 test relay R410 to open the previously described simplex circuit over which the line relay R740 of the link 21 is being held energized.

35 *Routing the call to a subscriber's line terminating at the subexchange 12*

If the call is to be routed to a substation, such, for example, as the substation T5 connected to a line terminating at the subexchange 12, the operator dials the two digits of the directory number designating the desired substation. In response to the impulses of the first digit, the connector switch 550 operates to position its wipers on the contacts terminating the conductors of the trunk line 17 extending to the 40 subexchange 12. Shortly following the end of this digit, the slow-to-release relay R455 restores to complete the previously traced operating circuit for the line switching and control relay R430. The last-mentioned relay, in turn, 45 operates to complete a circuit for energizing the relay R420 in series with the line switching relay R650 embodied in the line circuit associated with the trunk line 17, this circuit extending from ground by way of the winding of R420, RA432, 50 RC469, RA468, C487, the wiper 553, C592 and the winding of R650 to battery. The two relays R650 and R420 now operate to complete a simplex pulsing circuit extending from battery and through the resistor 333 for energizing the line 55 relay of the finder-connector link 25 provided in the subexchange 12. At RA653 and RC654, the relay R650 opens the previously traced path for impressing negative battery potential upon the trunk line conductor C604 following the completion of the simplex circuit just mentioned. Thus, the control apparatus of the link 25 is conditioned to respond to the impulses of the second digit dialed at the operator's position 15. At the 60 beginning of the first impulse of the second digit, the relay R455 is again energized and operates to complete the previously traced operating circuit for the digit transfer relay R460, which latter relay, in turn, operates to complete the 65

previously traced path for short-circuiting the winding of the relay R465. During the impulses of the second digit, the line relay R330 operates to repeat the dialed impulses over the above-mentioned simplex circuit to the line relay of the link 25, whereby the connector portion of this switch is caused to position its wipers on the contacts terminating the conductors of the called line 26. At the end of the second digit and when the relay R455 restores, the path short-circuiting the winding of the relay R465 is interrupted, permitting this relay to be energized in series with the winding of the relay R460. The relay R465 now operates to open, at RA466, a point in the operating circuit for the relay R460 and to complete, at RA467 and RA468, a holding circuit for the line switching relay R650, this holding circuit extending from ground at RA473 by way of RA467, RA468, C487, the wiper 553 and its associated second contact, C592, and the winding of R650 to battery. Following the completion of this circuit, the relay R465 functions to open, at RA468 and RC469, a point in the above-traced series circuit for energizing the respective windings of the two relays R420 and R650 in series, whereby the relay R420 is caused to restore. Upon restoring, the relay R420 interrupts, at RA421 and RA424 and their respective associated armatures RA422 and RA425, the above-described simplex circuit over which impulses are delivered to the line relay of the finder-connector link 25. At the armatures RA422 and RA425 and their respective associated contacts RC423 and RC426, the relay R420, upon restoring, completes an alternative simplex circuit extending by way of the impedance element 365, the repeater windings 363 and 364, and the link line conductors C398 and C399 for maintaining the line relay of the finder-connector link 25 operated for the duration of a call. Following the restoration of the relay R420 in the manner just described, the desired connection is fully completed between the calling substation T₄ and the called substation T₅. To signal the called subscriber that his substation is being called, the operator actuates her ringing key to cause ringing current to be projected over the two branches of the established connection, thereby to energize the signal device provided at both the calling and called substations. Finally, the desired talking circuit is completed when the calling and called parties operate the receivers provided at the calling and called substations to connect the telephone instruments respectively provided at these two substations to the calling and called lines 22 and 26, respectively.

At the end of the conversation and when the operator attending the position 15 receives the usual disconnect signal, she may operate the calling key 380 to its normal position, thereby to initiate the release of the automatic switching apparatus provided in the three exchanges 10, 11 and 12. When the switch 380 is restored to normal, the link 16 provided in the exchange 10 and the link 21 provided in the exchange 11 are caused to release in the exact manner set forth above. The manner in which the finder-connector link 25 provided in the exchange 12 is released is in all respects similar to the mode of release of the link 21 located in the exchange 11, it being pointed out that the release of the link 25 is initiated when the two relays R650 and R640 restore to open, respectively, the original operating circuit and the simplex holding circuit for the line relay embodied in this link.

Routing the call to another subscriber's line terminating at the subexchange 11

If the call as routed to the operator's position 15 from the calling substation T₄ is to be extended to a substation associated with another line terminating at the subexchange 11, the operator supervising the call dials the two digits of the directory number designating the called substation. For example, if the substation T₃ associated with the line 23 is the called substation, the operator dials the two digits of the directory number 12 designating the called line 23. In response to the single impulse of the first digit, the connector switch 550 positions its wipers on the contacts corresponding to the trunk line 14. At the end of the digit, the relay R450 restores to complete the previously traced operating circuit for the relay R430, which latter relay operates, in turn, to complete the previously traced circuit for energizing the winding of the relay R420 in series with the winding of the line switching relay R610 embodied in the line circuit associated with the trunk line 14. As a result, the conductors of the trunk line 14 are disconnected from the line wipers of the finder switch 500 and are connected by way of the conductors C581 and C585 and the connector line wipers 551 and 552 to the link line conductors C494 and C493, respectively. Since the relay R420 is also operated, the previously traced simplex circuit including the resistor 333 is completed for maintaining the line relay R740 of the link 25 operated. From this point on, the manner in which the impulses of the second digit are repeated by the line relay R330 over the simplex pulsing circuit to the line relay R740, to cause the wipers of the connector switch 850 to be positioned on the contacts terminating the conductors of the called line 23, is exactly the same as described previously with reference to the call routed to the substation T₄ associated with the line 22. At the end of the second digit and when the slow-to-release relay R830 embodied in the link 21 restores, a metallic connection is completed between the calling and called lines 22 and 23, respectively, this connection including the line wipers 801 and 802 of the finder switch 800, the link line conductors C864 and C866, the link line conductors C863 and C865, and the line wipers 851 and 852 of the connector switch 850. After the ringing operation is performed, the desired talking circuit is completed by way of this connection when the called subscriber lifts his receiver from its hook to answer the call and the calling subscriber lifts his receiver from its hook to cause his telephone instrument to be connected to the line 22. After the conversation is terminated, the automatic switching apparatus is released, in the exact manner previously described, when the operator attending the position 15 restores the calling key 380 to its normal position.

Call initiated at the operator's position 15

As indicated previously, calls routed to the operator's position 15 from the subscribers' lines terminating at the main or central exchange 9 may be routed to a line terminating at any one of the exchanges 10, 11 and 12 under the control of the operator attending the position 15. To this end, the operator may seize the automatic switching apparatus at a time when this apparatus is idle by operating the key 380 to its off-normal position to complete the previously traced simplex circuit for energizing the line relay R330. This relay, upon operating, initiates the sequen-

tional operation of the three relays R320, R470 and R440, in the manner previously explained. When the relay R440 operates, it opens, at RA442, a point in the previously traced operating circuit for the finder start relay R520, thereby to prevent this relay from operating in response to calls initiated on subscribers' lines extending to the tandem exchange 10. At RA441, the relay R440 completes the previously traced circuit extending by way of RA471 and C482 for energizing the lockout relay R640. The relay R640, upon operating, completes the previously traced paths for impressing negative battery potential upon each of the trunk line conductors C767 and C604 of the trunk lines 14 and 17, respectively. As a result, the control apparatus and, more particularly, the relays R740, R735, R710 and R755 embodied in the link 21 operate in the order named. The last-mentioned relay, upon operating, opens, at RA759, a point in the previously traced circuit for energizing the finder switch operating magnet 816. As a result, the finder switch of the link 21 is rendered nonresponsive to calls initiated on subscribers' lines extending to the subexchange 11. In a similar manner, the application of negative battery potential to the conductor C604 of the trunk line 17 results in the operation of the control apparatus embodied in the link 25 to render the finder switch of this link nonresponsive to calls initiated on the subscribers' lines extending to the exchange 12. Following the operation of the above-referred to relays, the call may be routed to any desired substation associated with a line terminating at any one of the three exchanges 10, 11 and 12 in the exact manner previously described with reference to the calls initiated at the substations T₁ and T₄. Also the manner in which the switching apparatus provided in the three exchanges 40 released when the operator restores the key 380 to its normal position is the same as previously described.

Call storing

As pointed out in the introductory portion of the specification, if a call is initiated on a line extending to one of the three exchanges 10, 11 and 12 at a time when the automatic switching apparatus provided in the tandem exchange 10 is busy, the call is stored until after the switching apparatus becomes idle and is then routed to the operator's position 15 without any further act on the part of the calling subscriber. Thus, if a call is initiated at the substation T₁ at a time when the link 16 is busy, the above-traced operating circuit for the finder start relay R520 is interrupted at each of the two operated armatures RA413 and RA442. Hence, the operation of the line relay R680 resulting from the ringing current projected over the line 18 through operation of the hand generator 693 is without effect to initiate the operation of the finder switch 500. In this case, however, since the line 18 is not involved in the previously established connection routed by way of the link 25, the conductor C577 is disconnected from ground so that the lower winding of the relay R680 is energized and the relay remains locked up in its operated position. Thereafter and during the release of the link 16, the last operation which occurs is the operation of the connector switch operating magnet 540 to return the wipers of the connector switch 550 to their respective home positions. During this operation, the wiper 554 is grounded over the path including

C485 and the restored armatures RA451 and RA457. As a result the lower winding of the operated relay R680 may be momentarily short-circuited while the wiper 554 is traversing its associated third contact. When, however, the lower winding of R680 is short-circuited, this relay is rendered slightly slow-to-release and since the wiper 554 is moving at a high rate of speed the short-circuiting path is interrupted before the relay R680 can restore. Hence, the release operation of the connector switch 550 does not result in the restoration of operated ones of line relays associated with subscribers' lines terminating at the exchange 10.

When the wiper 554 is returned to its home position and with the line relay R680 operated, the previously traced circuit is completed for energizing the finder start relay R520. Thus, the operation of the finder switch 500 to search for the calling line 18 is initiated immediately the link 16 is released. The manner in which the calling line is found and the call is forwarded to the operator's position 15 is exactly the same as described above with reference to the call initiated at the substation T₁ at a time when the automatic switching apparatus is idle.

In a similar manner, if a call is initiated on a line terminating at one of the subexchanges at a time when the automatic switching apparatus provided in the tandem exchange 10 is busy, the call is stored until the operated switching apparatus is released, after which it is automatically forwarded to the operator's position 15 in the main exchange 9. Under the conditions stated, the four relays R740, R735, R710 and R755 of the finder-connector link 21 are all operated. With the relay R755 in its operated position, the operating circuit for the finder switch operating magnet 816 is held open at RA759. Hence, if a call is initiated on one of the lines extending to the subexchange 11, such, for example, as the line 22, the resulting operation of the line relay R700 is only effective to cause the operation of the finder start relay R825. Upon operating, the relay R825 functions to prepare, at RA826, the operating circuit for the magnet 816, but the last-mentioned circuit is held open at RA759 until the operated link 16 provided in the exchange 10 is released to cause the release of the four relays R740, R735, R755 and R710 in the order named. When the relay R755 restores, it completes the operating circuit for the magnet 816 and prepares the operating circuit for the pulsing relay R820. Thus, operation of the finder switch 800 to seize the line 22 is initiated. From this point on, the manner in which the connection is forwarded to the operator's position 15 is exactly the same as described previously with reference to the call initiated at the substation T₄ at a time when the automatic switching apparatus provided in the three exchanges 10, 11 and 12 is idle.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, a first exchange, a second exchange, a plurality of lines extending to said first exchange, automatic switching apparatus in said first exchange operative to set up

- connections between said lines, said automatic switching apparatus including finder means normally operative to seize a calling one of said lines, a plurality of additional lines extending to said 5 second exchange, means in said second exchange for setting up connections between said additional lines, and means responsive to the initiation of a call on one of said additional lines for preventing said finder means from operating.
10. 2. In a telephone system, a first exchange, a second exchange, a trunk line interconnecting said exchanges, a plurality of lines extending to said first exchange, automatic switching apparatus in said first exchange operative to set up 15 connections between calling and called ones of said plurality of lines, said automatic switching apparatus including finder means normally operative to seize a calling one of said plurality of lines, a plurality of additional lines extending to 20 said second exchange, means in said second exchange for setting up connections between said additional lines, and means operative in response to the initiation of a call on one of said additional lines and controllable over said trunk line for 25 preventing said finder means from operating.
3. In a telephone system, a first exchange, a second exchange, a trunk line interconnecting said exchanges, a plurality of lines extending to said first exchange, automatic switching apparatus 30 in said first exchange operative to set up connections between calling and called ones of said plurality of lines, said automatic switching apparatus including finder means normally operative to seize a calling one of said plurality of lines, a plurality of additional lines extending to 35 said second exchange, automatic switching means in said second exchange for setting up connections between said additional lines, and means operative in response to the initiation of a call 40 on one of said additional lines and controllable over said trunk line for preventing said finder means from operating.
4. In a telephone system, a first exchange, a second exchange, a trunk line interconnecting 45 said exchanges, a plurality of lines extending to said first exchange, automatic switching apparatus in said first exchange operative to set up connections between calling and called ones of said plurality of lines, said automatic switching apparatus including finder means normally operative to seize a calling one of said plurality of lines, a plurality of additional lines extending to 50 said second exchange, automatic switching means in said second exchange for setting up connections between said additional lines, said automatic switching means including a finder switch 55 operative to seize a calling one of said additional lines and said trunk line, and means controllable over said trunk line and operative in response to the operation of said finder switch to seize a line other than said trunk line for preventing said finder means from operating.
5. In a telephone system, a first exchange, a second exchange, a trunk line interconnecting 60 said exchanges and including at least one conductor, a plurality of lines extending to said first exchange, automatic switching apparatus in said first exchange operative to set up connections between calling and called ones of said plurality of lines, said automatic switching apparatus including a finder switch of the step-by-step type 65 normally operative to seize a calling one of said plurality of lines, an operating magnet for said finder switch, an operating circuit for said magnet, means responsive to the application of a 70 predetermined potential to said one trunk line conductor.

- determined potential to said one trunk line conductor for opening a point in said operating circuit thereby to prevent said finder switch from operating, a plurality of additional lines extending to said second exchange, means in said second exchange for setting up connections between said additional lines, and means responsive to the initiation of a call on one of said additional lines for applying said predetermined potential to said one trunk line conductor. 5
6. In a telephone system, a first exchange, a second exchange, a trunk line interconnecting said exchanges and including at least one conductor, a plurality of lines extending to said first exchange, automatic switching apparatus in 15 said first exchange operative to set up connections between calling and called ones of said plurality of lines, said automatic switching apparatus including a finder switch of the step-by-step type normally operative to seize a calling one of said plurality of lines, an operating magnet for said finder switch, an operating circuit for said magnet, means responsive to the application of a predetermined potential to said one trunk line conductor for opening a point in said operating 20 circuit thereby to prevent said finder switch from operating, a plurality of additional lines extending to said second exchange, automatic switching means in said second exchange for setting up connections between said additional lines, said 25 automatic switching means including a second finder switch operative to seize a calling one of said additional lines and said trunk line, and means operative in response to the operation of said finder switch to seize a line other than said 30 trunk line for applying said predetermined potential to said one trunk line conductor.
7. In a telephone system, a first exchange, a second exchange, a trunk line interconnecting said exchanges and including at least one conductor, a plurality of lines extending to said first exchange, automatic switching apparatus in said first exchange operative to set up connections between calling and called ones of said plurality of lines, said automatic switching apparatus including a finder switch of the step-by-step type 40 normally operative to seize a calling one of said plurality of lines, an operating magnet for said finder switch, an operating circuit for said magnet, means responsive to the application of a predetermined potential to said one trunk line conductor for opening a point in said operating circuit thereby to prevent said finder switch from operating, a plurality of additional lines extending to said second exchange, automatic switching means in said second exchange for setting up connections between said additional lines, said automatic switching means including a second 45 finder switch operative step by step to search for a calling one of said additional lines, a line test relay included in said second finder switch and operative to arrest the stepping operation of said second finder switch when said second finder switch finds a calling line, and means responsive to the operation of said test relay for applying said predetermined potential to said one trunk line conductor. 55
8. In a telephone system, a first exchange, a second exchange, a plurality of lines extending to said first exchange, automatic switching apparatus in said first exchange operative to set up connections between said lines, said automatic switching apparatus including finder means normally operative to seize a calling one of said lines, a plurality of additional lines extend- 60

mined potential to said one trunk line conductor, means responsive to the initiation of a second call on one of said first-named plurality of lines at a time when a call is present on one of said additional lines for storing said second call, and means controlled jointly by said first-named means and said two last-named means for initiating the operation of said first finder switch to seize said one of said first-named lines when said second finder switch is released.

14. In a telephone system, a first exchange, a second exchange, a trunk line interconnecting said exchanges and including at least one conductor, a plurality of lines extending to said first exchange, automatic switching apparatus in said first exchange operative to set up connections between calling and called ones of said plurality of lines, said automatic switching apparatus including a first finder switch of the step-by-step type normally operative to seize a calling one of said plurality of lines, an operating magnet for said finder switch, an operating circuit for said magnet, means responsive to the application of a predetermined potential to said one trunk line conductor for opening a point in said operating circuit thereby to prevent said finder switch from operating, a plurality of additional lines extending to said second exchange, automatic switching means in said second exchange for setting up connections between said additional lines, said automatic switching means including a second finder switch operative step by step to search for a calling one of said additional lines, a line test relay included in said second finder switch and operative to arrest the stepping operation of said second finder switch when said second finder switch finds a calling line, means responsive to the operation of said test relay for applying said predetermined potential to said one trunk line conductor, means responsive to the initiation of a second call on one of said first-named plurality of lines at a time when a call is present on one of said additional lines for storing said second call, and means controlled jointly by said first-named means and said two last-named means for initiating the operation of said first finder switch to seize said one of said first-named lines when said second finder switch is released.

15. In a telephone system, a main exchange, a tandem exchange, a subexchange, trunk lines interconnecting said exchanges, a plurality of lines extending to said subexchange, automatic switching apparatus in said subexchange and controllable by way of said trunk lines from said main exchange to set up connections between calling and called ones of said plurality of lines, said automatic switching apparatus including finder means having access to said plurality of lines and normally operative to seize a calling one of said plurality of lines, a plurality of additional lines extending to said tandem exchange, automatic switching apparatus controllable over one of said trunk lines from said main exchange to set up connections between said additional lines, and means operative in response to the initiation of a call on one of said additional lines for preventing said finder means from operating.

16. In a telephone system, a main exchange, a tandem exchange, a subexchange, trunk lines interconnecting said exchanges, a plurality of lines extending to said subexchange, automatic switching apparatus in said subexchange and controllable by way of said trunk lines from said main exchange to set up connections between calling

and called ones of said plurality of lines, said automatic switching apparatus including finder means having access to said plurality of lines and normally operative to seize a calling one of said plurality of lines, a plurality of additional lines extending to said tandem exchange, automatic switching apparatus controllable over one of said trunk lines from said main exchange to set up connections between said additional lines, means operative in response to the initiation of a call on one of said additional lines for preventing said finder means from operating, means responsive to the initiation of a second call on one of said first-named plurality of lines at a time when a call is present on one of said additional lines for storing said second call, and means controlled jointly by said two last-mentioned means for initiating the operation of said finder means to seize said one of said first-named plurality of lines when the call on said one additional line is terminated.

17. In a telephone system, a main exchange, a tandem exchange, a subexchange, a first trunk line extending between said main and tandem exchanges, a second trunk line extending between said tandem and subexchanges, a plurality of lines extending to said subexchange, automatic switching apparatus controllable over said first and second trunk lines from said main exchange to set up connections between calling and called ones of said plurality of lines, said automatic switching apparatus including a first finder switch having access to said plurality of lines and normally operative to seize a calling one of said plurality of lines, a plurality of additional lines extending to said tandem exchange, automatic switching apparatus controllable over said first trunk line from said main exchange to set up connections between said additional lines, said last-named automatic switching apparatus including a second finder switch having access to said additional lines and operative to seize a calling one of said additional lines, and means controllable over said second trunk line and operative in response to the operation of said second finder switch to seize a calling one of said additional lines for preventing said first finder switch from operating.

18. In a telephone system, a main exchange, a tandem exchange, a subexchange, a first trunk line extending between said main and tandem exchanges, a second trunk line extending between said tandem and subexchanges, a plurality of lines extending to said subexchange, automatic switching apparatus controllable over said first and second trunk lines from said main exchange to set up connections between calling and called ones of said plurality of lines, said automatic switching apparatus including a first finder switch having access to said plurality of lines and normally operative to seize a calling one of said plurality of lines, a plurality of additional lines extending to said tandem exchange, automatic switching apparatus controllable over said first trunk line from said main exchange to set up connections between said additional lines, said last-named automatic switching apparatus including a second finder switch having access to said additional lines and operative to seize a calling one of said additional lines, means controllable over said second trunk line and operative in response to the operation of said second finder switch to seize a calling one of said additional lines for preventing said first finder switch from operating, means responsive to the initia-

tion of a second call on one of said first-named lines at a time when a call is present on one of said additional lines for storing said second call, and means controlled jointly by said two

5. last-named means for initiating the operation of said first finder switch to seize said one of said first-named lines when said second finder switch is released.

19. In a telephone system, a main exchange, a tandem exchange, a subexchange, a first trunk line extending between said main and tandem exchanges, a second trunk line extending between said tandem and subexchanges, a plurality of lines extending to said subexchange, automatic switching apparatus controllable over said first and second trunk lines from said main exchange to set up connections between calling and called ones of said plurality of lines, said automatic switching apparatus including a first finder switch having access to said plurality of lines and normally operative step by step to seize a calling one of said plurality of lines, an operating magnet in said finder switch, an operating circuit for said magnet, means responsive to the application of a predetermined potential to one conductor of said second trunk line for opening a point in said operating circuit, thereby to prevent said first finder switch from operating, a plurality of additional lines extending to said tandem exchange, automatic switching apparatus controllable over said first trunk line from said main exchange to set up connections between said additional lines, said last-named automatic switching apparatus including a second finder switch having access to said additional lines and operative to seize a calling one of said additional lines, and means operative in response to the operation of said second finder switch to seize a calling one of said additional lines for applying 40 said predetermined potential to said one trunk line conductor.

20. In a telephone system, a main exchange, a tandem exchange, a subexchange, a first trunk line extending between said main and tandem exchanges, a second trunk line extending between said tandem and subexchanges, a plurality of lines extending to said subexchange, automatic switching apparatus controllable over said first and second trunk lines from said main exchange
45 to set up connections between calling and called ones of said plurality of lines, said automatic switching apparatus including a first finder switch having access to said plurality of lines and normally operative step by step to seize a
50 calling one of said plurality of lines, an operating magnet in said finder switch, an operating circuit for said magnet, means responsive to the application of a predetermined potential to one conductor of said second trunk line for opening
55 a point in said operating circuit, thereby to prevent said first finder switch from operating, a plurality of additional lines extending to said tandem exchange, automatic switching apparatus controllable over said first trunk line from said
60 main exchange to set up connections between said additional lines, said last-named automatic switching apparatus including a second finder switch having access to said additional lines and operative to seize a calling one of said additional lines, means operative in response to the operation of said second finder switch to seize a calling one of said additional lines for applying said predetermined potential to said one trunk line conductor, means responsive to the initiation of
65 a second call on one of said first-named lines at
70

a time when a call is present on one of said additional lines for storing said second call, and means controlled jointly by said two last-named means for initiating the operation of said first finder switch to seize said one of said first-named lines when said second finder switch is released. 5

21. In a telephone system, a main exchange, a tandem exchange, a subexchange, a first trunk line extending between said main and tandem exchanges, a second trunk line extending between said tandem and subexchanges, a plurality of lines extending to said subexchange, automatic switching apparatus controllable over said first and second trunk lines from said main exchange to set up connections between calling and called ones of said plurality of lines, said automatic switching apparatus including a first finder switch having access to said plurality of lines and normally operative step by step to seize a calling one of said plurality of lines, an operating magnet in said finder switch, an operating circuit for said magnet, means responsive to the application of a predetermined potential to one conductor of said second trunk line for opening a point in said operating circuit, thereby to prevent said first finder switch from operating, a plurality of additional lines extending to said tandem exchange, automatic switching apparatus controllable over said first trunk line from said main exchange to set up connections between said additional lines, said last-named automatic switching apparatus including a second finder switch having access to said additional lines and operative step by step to search for a calling one of said additional lines, a line test relay included in said second finder switch and operative to arrest the stepping operation of said second finder switch when said second finder switch finds a calling line, and means responsive to the operation of said test relay for applying said predetermined potential to said one trunk line conductor. 10 15 20 25 30 35 40

22. In a telephone system, a main exchange, a tandem exchange, a subexchange, a first trunk line extending between said main and tandem exchanges, a second trunk line extending between said tandem and subexchanges, a plurality of lines extending to said subexchange, automatic switching apparatus controllable over said first and second trunk lines from said main exchange 45 to set up connections between calling and called ones of said plurality of lines, said automatic switching apparatus including a first finder switch having access to said plurality of lines and normally operative step by step to seize a calling one 50 of said plurality of lines, an operating magnet in said finder switch, an operating circuit for said magnet, means responsive to the application of a predetermined potential to one conductor of said second trunk line for opening a point in said operating circuit, thereby to prevent said first finder switch from operating, a plurality of additional lines extending to said tandem exchange, automatic switching apparatus controllable over said first trunk line from said main exchange to set 60 up connections between said additional lines, said last-named automatic switching apparatus including a second finder switch having access to said additional lines and operative step by step to search for a calling one of said additional lines, a 65 line test relay included in said second finder switch and operative to arrest the stepping operation of said second finder switch when said second finder switch finds a calling line, means responsive to the operation of said test relay for 70 75

appling said predetermined potential to said one trunk line conductor, means responsive to the initiation of a second call on one of said first-named lines at a time when a call is present on 5 one of said additional lines for storing said second call, and means controlled jointly by said two last-named means for initiating the operation of said first finder switch to seize said one of said first-named lines when said second finder 10 switch is released.

23. In a telephone system, a main exchange, a tandem exchange, a subexchange, trunk lines interconnecting said exchanges, a plurality of lines extending to said subexchange, automatic switching apparatus in said subexchange operative to set up connections between calling and called ones of said plurality of lines, said automatic switching apparatus including finder means having access to said plurality of lines and normally 15 operative to seize a calling one of said plurality of lines, a plurality of additional lines extending to said tandem exchange, means in said tandem exchange for setting up connections between said additional lines, one of said trunk lines extending 20 between said tandem exchange and said main exchange, and means responsive to the initiation of a call on said one of said trunk lines for preventing said finder means from operating.

24. In a telephone system, a main exchange, a tandem exchange, a subexchange, trunk lines interconnecting said exchanges, a plurality of lines extending to said subexchange, automatic switching apparatus in said subexchange operative to set up connections between calling and called 30 ones of said plurality of lines, said automatic switching apparatus including finder means having access to said plurality of lines and normally operative to seize a calling one of said plurality of lines, a plurality of additional lines extending to said tandem exchange, automatic switching means in said tandem exchange for setting up 35 connections between said additional lines, said automatic switching means including finder means having access to said additional lines and normally operative to seize a calling one of said additional lines, one of said trunk lines extending between said tandem exchange and said main exchange, and means responsive to the initiation of a call on said one trunk line for preventing both of said finder means from operating.

25. In a telephone system, a main exchange, a tandem exchange, a subexchange, trunk lines interconnecting said exchanges, a plurality of lines extending to said subexchange, automatic switching apparatus in said subexchange operative to set up connections between calling and called ones of said plurality of lines, said automatic switching apparatus including finder means 55 having access to said plurality of lines and normally operative to seize a calling one of said plurality of lines, a plurality of additional lines extending to said tandem exchange, automatic switching means in said tandem exchange for setting up connections between said additional lines, said automatic switching means including finder means having access to said additional lines and normally operative to seize a calling one of said additional lines, one of said trunk lines extending 60 between said tandem exchange and said main exchange, means responsive to the initiation of a call on said one trunk line for preventing both of said finder means from operating, means responsive to the initiation of a second call on one 65 of said first-named plurality of lines or one of

said additional lines at a time when said one trunk line is busy for storing said second call, and means for initiating the operation of the finder means having access to the line upon which said second call originates when the busy condition 5 of said one trunk line is terminated.

26. In a telephone system, a main exchange, a tandem exchange, a subexchange, a first trunk line extending between said main and tandem exchanges, a second trunk line extending between 10 said tandem and subexchanges and including at least one conductor, a plurality of lines extending to said subexchange, automatic switching apparatus in said subexchange for setting up connections between calling and called ones of said 15 plurality of lines, said automatic switching apparatus including a finder switch normally operative step by step to seize a calling one of said plurality of lines, an operating magnet in said switch, an operating circuit for said magnet, lock-out means responsive to the application of a predetermined potential to said one conductor for opening a point in said operating circuit, thereby to prevent said finder switch from operating, additional lines extending to said tandem exchange, 20 means in said tandem exchange for setting up connections between said additional lines, and means responsive to a call initiated on said first trunk line for applying said predetermined potential to said one trunk line conductor. 30

27. In a telephone system, a main exchange, a tandem exchange, a subexchange, a first trunk line extending between said main and tandem exchanges, a second trunk line extending between 35 said tandem and subexchanges and including at least one conductor, a plurality of lines extending to said subexchange, automatic switching apparatus in said subexchange for setting up connections between calling and called ones of said 40 plurality of lines, said automatic switching apparatus including a finder switch normally operative step by step to seize a calling one of said plurality of lines, an operating magnet in said switch, an operating circuit for said magnet, lockout means responsive to the application of a 45 predetermined potential to said one conductor for opening a point in said operating circuit, thereby to prevent said finder switch from operating, additional lines extending to said tandem exchange, means in said tandem exchange for 50 setting up connections between said additional lines, means responsive to a call initiated on said first trunk line for applying said predetermined potential to said one trunk line conductor, means responsive to the initiation of a second call on 55 one of said first-named plurality of lines at a time when said first trunk line is busy for storing said second call, and means controlled jointly by said last-named means and said lockout means for initiating the operation of said finder switch 60 to seize said one of said first-named plurality of lines when the busy condition of said one trunk line is terminated.

28. In a telephone system, a main exchange, a tandem exchange, a subexchange, a first trunk line extending between said main and tandem exchanges, a second trunk line extending between 65 said tandem and subexchanges and including at least one conductor, a plurality of lines extending to said subexchange, automatic switching apparatus in said subexchange for setting up 70 connections between calling and called ones of said plurality of lines, said automatic switching apparatus including a first finder switch normally 75

- operative step by step to seize a calling one of said plurality of lines, an operating magnet in said switch, an operating circuit for said magnet, lockout means responsive to the application of 5 a predetermined potential to said one conductor for opening a point in said operating circuit, thereby to prevent said first finder switch from operating, additional lines extending to said tandem exchange, automatic switching means in said 10 tandem exchange for setting up connections between said additional lines, said automatic switching means including a second finder switch operative to search for a calling one of said additional lines, means responsive to the initiation of 15 a call on one of said additional lines for applying said predetermined potential to said one trunk line conductor, and means responsive to the initiation of a call on said first trunk line for applying said predetermined potential to said 20 one trunk line conductor and for preventing said second finder switch from operating.
29. In a telephone system, a main exchange, a tandem exchange, a subexchange, a first trunk line extending between said main and tandem exchanges, a second trunk line extending between said tandem and subexchanges, a plurality of lines extending to said subexchange, automatic switching apparatus in said subexchange for setting up 25 connections between calling and called ones of said plurality of lines, a plurality of additional lines extending to said tandem exchange, automatic switching apparatus in said tandem exchange and controllable over said first and second trunk lines from said main exchange to set up connections between calling and called ones of said plurality of lines, a plurality of additional lines extending to said tandem exchange, automatic switching apparatus in said tandem exchange and controllable over said first trunk line from said main exchange to set up connections between 30 said additional lines, said last-named switching apparatus including a finder switch having access to said additional lines and normally operative to seize a calling one of said additional lines and said second trunk line, said 35 finder switch being seized in response to the initiation of a call on one of said first-named plurality of lines and thereby rendered inoperative to seize one of said additional lines, means responsive to the initiation of a second call on one of said additional lines at a time when a call 40 is present on one of said first-named plurality of lines for storing said second call, and means for initiating the operation of said finder switch to seize the line upon which said second call originates when the call on said one of said first-named plurality of lines is terminated and said 45 finder switch is released.

EDWARD S. PETERSON.
